UNITED STATES PATENT OFFICE

2,498,041

SEWING MACHINE

Clyde L. Knott, Beverly, Mass., assignor to United
Shoe Machinery Corporation, Flemington, N. J.,
a corporation of New Jersey

Application January 10, 1945, Serial No. 572,119

137 Claims. (Cl. 112—36)

1
The present invention relates to sewing machines and particularly to lockstitch shoe sewing machines of the McKay type employing a straight hook needle and a rotatable shoe entering and supporting horn in which each stitch is formed and set in the work during a single sewing cycle, as in the machines of prior United States Letters Patent granted on applications of Lawrence E. Topham, No. 2,094,030, on September 28, 1937, and of the present inventor, No. 2,159,166, on May 23, 1939, although in certain of its features, the invention is applicable generally to sewing machines of the McKay or other types.

The machines of the patents are distinguishable from other McKay type sewing machines, such as those disclosed in United States Letters Patent No. 1,885,927, granted November 1, 1932, on an application of Bernard T. Leveque, and No. 2,331,118, granted October 5, 1943, on an application of Joseph Gouldbourn and Thomas A. Kestell, in which a stitch is formed during one sewing cycle or rotation of the main sewing shaft, and not completed and set in the material operated upon until a subsequent sewing cycle. In the present type of machine, as disclosed in the first two mentioned patents, each stitch is formed and set in the material operated upon during a single sewing cycle or rotation of the main sewing shaft without undesirable effects on the thread produced by slipping in the needle hook or in the previously formed stitch as the threaded hook is being drawn through the work and presented to the loop taker or shuttle.

In order to enable each stitch to be formed and set in a single sewing cycle of a lockstitch McKay type shoe sewing machine without causing the thread to slip or slide in the hook of the needle while each loop of needle thread is being drawn through the work or in the previously formed stitch, it appears to be necessary to employ a thread finger in the tip of the rotatable horn and to rotate the needle into a position corresponding to the rotary position of the horn before laying the thread in the needle hook so that a bight of thread temporarily held by the thread finger will always extend between the work and the threaded needle uniformly from the same side of the needle hook.

The objects of the present invention are not only to improve generally the construction and the mode of operation of a machine of the McKay type arranged to cause each stitch to be set in the work during the same sewing cycle in which the stitch is formed, but also to provide a machine which may be operated satisfactorily at

2
speeds higher than heretofore employed and with results in accuracy and uniformity of stitch location in the work not previously obtainable in McKay type or other lockstitch shoe sewing machines.

Where a rotatable McKay type shoe entering and supporting horn is employed in a shoe sewing machine, there always has been difficulty in controlling by means of the usual stitch forming and setting devices, the location in the material operated upon at which, and the tension of the thread with which, the stitches are set. These devices, according to general practice, comprise amongst others, a straight hook needle, a needle threading whirl, a needle thread lock and a take-up acting with or without a pull-off at the side of the work with the horn, which pull-off measures thread in proportion to the thickness of the work. The outside dimensions of the horn in a McKay type sewing machine must be kept relatively small in order to enable the horn tip to be accommodated readily during sewing operations within the toe of a small size shoe. Thus, little, if any space is available for convenient location close to the work within the horn of the thread lock, take-up or pull-off devices in addition to the needle threading whirl. For this reason, the thread lock, take-up and pull-off devices generally are located outside or beneath the horn at a distance from the work, the length of thread between the work and the said devices being so great that, due to natural resiliency of the thread, the total amount of thread elongation resulting at the time of applying the setting tension to each stitch frequently is greater than the thread consumed by the stitch. Slight irregularities in stretching quality of the thread or irregularities in frictional effect on the thread may thus cause wide uncontrollable variations in depth of location and degree of tension to which successive stitches are set in the work.

The space required by a rotatable shoe entering horn at one side of the work necessitates locating both the needle and the work feeding instrument of a McKay type machine upon the opposite side of the work and some compromise ordinarily is made in the design of the work feeding instrument and its operating mechanism in order not to interfere with the needle and presser foot actuating mechanisms. Such compromise does not contribute to accuracy of work feed, and since the amount of thread required for each stitch is dependent not only upon the thickness of the work but also upon the length of work feed, inaccuracy of feed length caused by com-

promised design in the feeding mechanism impresses undesirable limitations on the accuracy of stitch location and thread tension, particularly when the machine is operated at high speeds.

One particular object of the invention is to provide a lockstitch shoe sewing machine of the McKay type, with features useful in sewing machines of the McKay type as well as of other types, in which a novel and improved construction and operation of the work feeding mechanism enables feeding movements to be imparted to the work between stitches more uniformly in length than heretofore considered possible. A further object is to connect the work feeding mechanism with the thread measuring devices of a lockstitch shoe sewing machine to insure location of successive stitches in the work automatically at a fixed predetermined depth regardless of the length of stitches for which the work feeding mechanism is adjusted.

A still further object of the invention is to provide novel and improved mechanisms acting in a shoe sewing machine after the stitch forming devices of the machine have been brought to rest to sever the thread, to set the final stitch of a seam in the work without starting any new stitch forming operations, such as puncturing the work, and to perform certain operations incidental to the satisfactory completion of one seam, and other operations preparatory to the beginning of another seam. The performance of these incidental operations, and particularly that of setting the final stitch, in prior sewing machines, either has not been attempted, the final stitch remaining loose, or has been accomplished during the final movements of the machine by the action of momentum in the operating parts just before the machine comes to rest or by manipulations of the operator thereafter. Where momentum is dependent upon for power to complete the incidental operations at the end of a seam, there is no positive assurance that these operations will be completed uniformly when the machine is running at a lower than normal sewing speed just prior to stopping. By the use of the present improvements to be described hereinafter more fully which act without reliance upon momentum in the operating parts of the machine after the machine stops, the final stitch is set and the threads are severed by mechanism separate from the mechanisms for performing the usual sewing operations.

With the above and other objects in view, an important feature of the present invention contemplates the provision in a shoe sewing machine having a curved work penetrating instrument acting to puncture the work for the needle of a mounting for the instrument to guide the point of the instrument along a path concentric to its curvature to penetrate the work and along a path within the plane of its curvature to feed the work. Such construction is advantageous, when no awl is employed and if a curved needle is used instead of the awl as the only work penetrating instrument. On account of the inherent stiffness of a curved penetrating instrument and its mounting against forces acting within the plane of curvature of the instrument, more nearly uniform stitch spacing is possible than when the stiffness of the instrument and its mounting is relied upon to resist forces acting at right angles to its plane of curvature as with a laterally feeding needle or awl of prior shoe sewing machines. This feature is especially useful in a McKay type

shoe sewing machine employing a straight needle where an awl must of necessity be mounted to operate at the same side of the work with the needle and at the opposite side of the work from a rotatable work supporting horn. When utilized in this type of machine, the radius of curvature of the awl is made sufficiently large to bring the work engaging portion of the awl into substantial line with the straight needle and, at the same time, the curved path within which the awl is actuated diverges sufficiently from the needle path to clear the needle during awl retraction from the work without any necessity for delaying the work penetrating stroke of the needle excessively in each sewing cycle. Preferably, the mechanism for actuating the awl to feed the work causes the point of the awl to move along a path not only within the plane of awl curvature in the direction of feed, but also at a slight inclination to the work supporting surface of the work support so that the pressure of the work on the work support produced during the penetrating stroke of the awl will be relieved for easy feeding movement. This mechanism, in its illustrated form, comprises a linkage, including a carrier for the awl, a linkage member on which the awl carrier is pivoted to swing towards and from the needle, a radius arm for guiding the awl carrier in a path concentric with the awl curvature extending towards and from the work, and a feeding lever to which the radius arm is connected. On account of the general arrangement of the needle, awl and awl actuating connections, and of the pivotal mountings for said connections on the frame of the machine, according to the particular construction of awl actuating mechanism hereinafter described, the awl, while feeding the work tends to withdraw to some extent from the work. To offset withdrawal movement of the awl while feeding the work, in the form of the connections illustrated, a compensating link is connected to the awl feeding lever acting to reduce such movement to an extremely limited amount.

As in prior machines, the awl feeding lever is actuated by a mechanism which is adjustable to change the length of feeding movement. The compensating link in the machine described hereinafter is so connected with the feeding lever that no substantial change will occur in the depth to which the awl penetrates the work.

The particular system of connections in the present machine comprising the mechanism for actuating and guiding the awl is of the type commonly known as a four-bar linkage, one bar of which includes the frame of the machine, another the carrier for the awl, and two others, separate members of different lengths connected between spaced pivots on the awl carrier and relatively fixed pivots on the frame, the shorter member consisting of the linkage member above referred to and being more remote from the awl than the longer one. With a four-bar linkage of this construction, the geometrical center about which the awl oscillates may be located at or about the level of the work supporting surface of the horn without in any way obstructing the movements of the work, the pivotal mountings of the linkage members being spaced substantially above the work supporting surface and in the direction of feed, out of the path of needle operation. Thus the actual path of the awl point adjacent the work support is made substantially perpendicular to the surface of the work support so that a straight needle may be employed, the operating

path of which is substantially tangent with the portion of the awl path intersecting the work. Not only is the resistance against bending of the awl greater within its plane of curvature when it is so actuated and guided, but the pivots for the awl linkage all are arranged parallel to the geometrical axis about which the awl oscillates during work penetrating and withdrawing movements. For these reasons there will be no undesirable twisting or shearing forces applied to the pivots and a construction of inherent rigidity results with assurance that a full depth penetration of the work will occur during each oscillation of the awl. With a rigid construction and substantially full depth penetration of the work, a better and more uniform feeding movement is imparted to the work so that the measurement of thread may fit more exactly with the requirements of the work.

As a further means for insuring that successive stitches will be set at a uniform location in the work, the awl actuating mechanism in the present machine is connected to a locking thread pull-off device which is actuated during formation of each stitch to withdraw a measured length of locking thread from a supply within a needle thread loop taker or shuttle. This feature of the invention is embodied in a machine having one mechanism for actuating the awl towards and from the work to cause the awl to penetrate the work and another mechanism including adjustable connections for actuating the awl in the line of the seam to feed the work, the locking thread pull-off device being driven by the adjustable work feeding connections so that the amount of locking thread pulled off will vary automatically with the length of feeding movement imparted by the awl. According to this feature of the invention, the pull-off device is actuated by two separate trains of connections, one of which causes a length of thread to be pulled off substantially equal in amount to that required in drawing each stitch to a fixed depth in the work, and another of which actuates the device to pull off a length of thread equal to the distance between successive stitches. In the present form of this feature, the train of connections which causes thread to be pulled off corresponding in amount to that required in drawing the stitch to a fixed depth in the work operates while the stitch is being set, and the train of connections which measures thread equal to the distance between successive stitches acts during feeding movement of the work. The use of a separate train of connections for actuating the pull-off device to measure thread for the depth of the stitch enables a more accurate measurement of thread to be obtained than where the entire thread measurement is provided by connections operated solely by a single adjustable train of connections comprising the awl feed mechanism. When the length of the awl feeding movement is changed, with the present arrangement of connections, a corresponding change in the same ratio occurs in the amount of thread measured, while the amount measured for the depth of the stitch remains fixed. Thus no variation occurs in the character of the stitch while the awl feed mechanism is being adjusted, the depth to which the stitch is intended to be set being maintained the same for all lengths of feeding movement.

In one embodiment of this feature of the invention the train of connections for causing the pull-off to measure thread for the depth of stitch comprises a crank on the main sewing shaft of

the machine and the train of connections for causing the pull-off device to measure thread for the distance between stitches is actuated advantageously by a cam, which as a matter of convenience, is the same as that employed to impart the work-feeding movements to the awl mechanism. In another embodiment of this feature, two cams are employed, one to actuate the train of connections which causes thread to be measured for the depth of stitch, and the other train which causes the thread to be measured for the length of stitch.

The thread measuring pull-off device, in its illustrated form, consists of thread gripping jaws 15 timed and actuated along the lead of the locking thread passing from the thread case to the work to withdraw thread from the supply after each needle loop is pulled from the loop taker. Preferably, the jaws remain in gripping engagement with the thread while the stitch including said needle loop is being set. By timing and actuating the locking thread measuring device in this way, actual engagement of the jaws with the locking thread occurs only during a relatively 20 short portion of each sewing cycle, in the remainder of which the locking thread and loop taker are free from any such obstruction as would interfere with easy passage of a needle loop about the loop taker.

30 While many of the features of invention relating to the awl, the locking thread pull-off devices and their actuating mechanisms are most effective when employed in connection with a lockstitch McKay type shoe sewing machine constructed and arranged to be operated as disclosed in the patents referred to, certain of the features are applicable with substantial advantage to other lockstitch sewing machines or to chainstitch machines. Certain other features, including a 35 novel and improved presser foot actuating mechanism described more fully hereinafter, relate more particularly to improvements useful in McKay type shoe sewing machines generally.

In addition to the improvements in the awl and 40 thread pull-off devices and their actuating mechanisms above referred to, still other features of the present invention relate to a novel and improved arrangement of loop lifter, spreader and loop taker with their supporting and actuating mechanisms, to a novel and improved thread cutter with a mechanism for actuating and controlling the same in a manner more convenient and effective than heretofore, to a simplified and improved form of needle rotating mechanism, to 45 a supporting frame particularly useful with the type of machine above identified and to certain constructions, combinations and arrangements of parts hereinafter described and claimed, the advantages of which will be obvious to those skilled 50 in the art from the following description, taken in connection with the drawings, in which

The machine illustrated in the drawings is a lockstitch McKay type shoe sewing machine similar in many respects to the machine disclosed in the patents to Topham and to the present inventor, above identified. Many of the parts and mechanisms of the machine, such as the work supporting horn and its enclosing devices and the work clamping and releasing presser foot are the same as those described more in detail in these patents, these parts and mechanisms being referred to only briefly in the following description. The mechanism for driving the machine and bringing the stitch forming devices to rest at the end of a seam are substantially the same as disclosed in United States Letters Patent No. 2,332,649, granted October 26, 1943, upon an application of the present inventor, which mechanism is arranged to act under the control of a foot treadle 2 to drive the machine selectively at either of two speeds or to bring the machine to rest by first reducing the speed of the machine below the lowest driving speed and then by disconnecting the machine from its driving mechanism. The rotary work supporting horn of the illustrated machine, indicated at 4 in Fig. 16, contains a needle threading looper 6, a thread finger 8, a take-up 10, a fixed light tension 11 (see Fig. 16), and a variable heavy thread tension 12 (see Fig. 15), together with the actuating mechanisms therefor, described more fully in United States Letters Patent No. 2,159,166, granted May 23, 1939, upon an application filed in the name of the present inventor.

In the machine of inventor's patents referred to, the work is fed step by step through the operation of a feed point at the side of the work with the presser foot and needle acting to produce a shallow puncture in the upper surface of the work a stitch length from the needle and to move the work a stitch length with the puncture brought into line with the needle. In order to prevent the feed point from damaging the work, mechanism is provided for adjusting the depth to which the feed point enters the work as the thickness of the work varies from stitch to stitch. Not only does the shallow puncture produced by the feed point leave a substantial thickness of work remaining to be penetrated by the needle of the machine, but due to the relatively insecure grip obtained on the work by reason of the shallowness of the puncture, there is an opportunity for the feed point to tear the surface of the work causing a series of irregular gashes, the distance between stitches being thereby shortened and varied by the lengths of the gashes.

An important feature of the present invention relates to improved mechanisms in a McKay type shoe sewing machine for puncturing needle receiving perforations extending substantially through the work at right angles to the surface of the work support and for causing the work to be fed in uniform amounts during each stitch forming cycle. In order to puncture needle receiving perforations, the work must be penetrated substantially through and, consequently, the work is engaged by a curved awl 14 (see Fig. 51) having a relatively large radius of curvature as compared to that of awls in prior sewing machines.

11

The awl 14 of the illustrated machine is actuated by mechanism for causing the awl point, while entering the work, to move through a path, including a penetrating stroke indicated at 15, concentric with the curvature defined by the inner side of the awl. To feed the work, the awl is moved a stitch length bodily with its point describing a path 16 within the plane of awl curvature, to bring the perforation formed by the awl into substantial alignment with the needle 18 (Figs. 17, 18 and 48) which is of the conventional hooked and straight shank type. The greatest possible rigidity in construction for any given size of curved awl is obtained in moving the awl within its plane of curvature when the outer side of the awl faces the needle and moves into line with the needle to feed the work, for the reason that the force applied to the awl reacts upon an arc formed by its curvature.

In order to actuate the curved awl in a path concentric to its curvature and within its plane of curvature to feed the work in this way, the center about which the awl moves must be located at approximately the level of the work a short distance from the sewing point. Such location of an actual fixed central pivot for the awl is prohibitive, so far as practical sewing operations are concerned, since it would interfere with proper presentation of the work to the machine. Accordingly, an awl actuating mechanism and a guiding mounting are provided in the machine embodying the present invention which avoids so locating a pivot for the awl and which enables the same motion to be imparted to the awl as if there were a fixed central pivot without interfering with the proper presentation of the work to the machine.

Referring to Figs. 3, 4 and 51, the illustrated mechanism and mounting for actuating and guiding the awl throughout its work penetrating and retracting stroke comprise a four-bar linkage including the frame 19 of the machine, a carrier 20 to which the awl is secured, and two linkage members 22 and 24 of different lengths connected by spaced pivots 26 and 28, respectively, on the awl carrier 20. The shorter linkage member 22 is in the form of an arm secured to the forward end of a horizontal rockshaft 30 rotatable in the machine frame and arranged to be oscillated through connections with a horizontal main sewing shaft 32 extending toward the front of the machine. The longer member 24 is a link in the nature of a radius arm connecting the pivot 28 with a pivot 34 mounted in a feed lever 36, the hub of which is fast to a shaft 38 rotatable in the machine frame, the pivot 34 being held stationary during the work penetrating stroke. The lever 36 comprises one member of the work feeding mechanism and is held stationary throughout the greater portion of each rotation of the main sewing shaft and, when actuated, causes the radius arm 24 to move the awl point along the line of feed, swinging the awl carrier 20 about the pivot 26.

The construction and arrangement of the four-bar linkage mounting for guiding the awl is such that, if the shorter member or arm 22 could be rotated through 360° without restriction by the actuating connections, the point of the awl would describe a non-symmetrical circuit, indicated at 40 in Fig. 50. However, the oscillating movement of the rockshaft 30 is so restricted due to the nature of the actuating connections that the movement of the awl is confined to a portion of the circuit 40 between points 42 and 44, which

12

corresponds to the penetrating stroke 15. This portion of the circuit 40 has a curvature closely approximating the arc of a circle, the center of which, in the construction shown, is located approximately at the level of the work and produces substantially the same effect as an actual fixed pivot located at the level of the work.

To insure that the needle will not be subject to undesirable strains necessitating the use of a needle size larger than required for the thread employed, the work engaging portion of the awl is formed with a main curved body of circular section and a straight edged lateral projection or flange 46 extending lengthwise of the circular section along the outer convexly curving side surface of the body (see Fig. 31). The straight edged projection increases in width along the length of the awl until a point is reached corresponding to the depth of awl penetration for the thickest possible work and the projection merges with the awl curvature a substantial distance from the point. Above the work engaging portion of the awl is a curved shank, of square section, the sides of which form angles of about 45° with the line of feed, the shank portion entering into a clamp socket formed by a cap plate 48 and a groove in the lower end of the awl carrier 20 (see Fig. 53). The cap plate is secured against the awl by a clamp screw 50.

The connections of the awl actuating mechanism between the main sewing shaft 32 and the rockshaft 30 comprise an arm 52 on the rearward end of the rockshaft inside the frame of the machine and a link 54 pivotally connected, in a manner further described below, between the arm 52 and one of a pair of toggle links 56 and 58, the central joint of which is pivotally connected to a pitman 60 mounted on a crank 62 on the sewing shaft 32. The toggle link 58 is secured to a horizontal shaft 64 rotatable in bearings in the machine frame and is moved towards and from alignment with the link 56 during rotation of the main sewing shaft to cause the awl to penetrate and withdraw from the work.

To impart a work feeding movement to the awl while engaging the work, the pivot 34 for the radius arm 24 is moved to change the position of the awl along the line of feed. For this purpose, the shaft 38 which carries the feed lever 36 is rotated in a counterclockwise direction, swinging the pivot 34 upwardly and to the left as viewed in Fig. 51. The mechanism for imparting the feeding movement to the shaft 38 and feed lever 36 comprises a dovetailed slide 66 adjustably clamped in a calibrated guideway 68 on the left side of the lever. A link 70 connects the upper end of the slide 66 to a similar slide 72 clamped in a similar calibrated guideway 74. The guideway 74 forms a part of a cam lever 76 comprising also a stud 78 rotatable in the machine frame and one arm of the lever carries a cam roll 80 engaging a suitably shaped track cut in a cam 82 (see Fig. 5) on the main sewing shaft 32.

On account of the angular relation of the awl carrier 20 with the surface of the work being operated upon, there is, in addition to the movement imparted in the direction of feed by the feed lever to the awl, a substantial component of movement tending to withdraw the awl from engagement with the work. In order to prevent withdrawal of the awl from the work during feeding movement, the feed lever 36 has an arm of short radius pivotally connected with one end of a compensating link 84, the other end of which carries two pivots 86 and 88. The pivot 86 on

the compensating link is connected to one end of the toggle link 56. The pivot 88 engages the connecting link 54, the arrangement being such that while the awl is feeding the work a slight additional movement is imparted to the awl actuating connections, including the linkage member 22, in a downward direction to offset the movement tending to withdraw the awl from the work.

The resulting motion of the awl oscillating mechanism and the feeding mechanism causes the point of the awl to move along a closed wedge-shaped path, indicated by dot-dash lines in Fig. 51, within the plane of curvature of the awl having, in addition to the curved penetrating stroke 15 at one side, a second curved withdrawing stroke 90 substantially parallel to the awl. The lower end portion 16 of the wedge-shaped path comprises the work feed, and the uppermost end portion 91 corresponds to the back feeding movement of the awl. Along the wedge-shaped upper end of the awl path, the back feeding movement of the awl merges with the withdrawing stroke and eventually comes into line with the penetrating stroke, the feeding movement being substantially at right angles to the penetrating and withdrawing strokes.

In order to relieve the pressure of the work against the upper surface of the horn 4 exerted in resisting the penetration of the awl, the location of the pivots 86 and 88 of the compensating link 84 is arranged to cause the feeding movement 16 of the awl to be inclined slightly upwardly through a small angle with relation to the upper surface of the work support. The lower end of the work penetrating stroke of the awl, however, reaches sufficiently close to the work supporting surface of the horn to insure substantially complete penetration of the work, leaving only an extremely thin section of the work for the needle to break through before entering the needle receiving opening in the horn.

The positions of the slides 66 and 72 in their respective guideways determine the length of feeding movement imparted to the awl during each sewing cycle. To change the feeding movement the slides are moved by equal amounts with their 0-marks opposite identical markings on their respective indicating scales along the guideways 68 and 74. To secure the slides in the guideways a circular opening at one side of each guideway is fitted with a flat sided washer 92 surrounding a clamping bolt 94 threaded into the hub of the respective levers. The flat sides of the washers 92 engage the corresponding slides when the clamp bolts are tightened and hold the slides in place.

In shoe sewing machines employing a hook needle, it is desirable to utilize as small a needle as possible in proportion to the size of the sewing thread and to avoid so far as possible sliding movement of the thread through the needle hook. A common method of preventing sliding movement of the thread in the hook of the needle in McKay type of sewing machines employing a rotatable shoe supporting horn is to leave the preceding stitch loose in the work and to draw thread from that stitch as well as from the supply, in retracting the threaded needle from the work for the succeeding stitch. In this way a supply of thread is available at both sides of the needle so that there is less tendency for the thread to be pulled through the needle hook while being retracted from the work. This is the method of operation in the machines of the

Leveque and Gouldbourn et al. patents above referred to. In this form of machine, the feeding movement of the work necessarily must take place after each stitch is formed and before that stitch is set. Consequently, the stitch which is being set always is out of alignment with the needle and the needle receiving opening in the horn, the thread being drawn around a number of corners and perforations in the work and between the work and the work supporting surface of the horn so that there is danger of breakage or abrasion on the thread. Also, there is a tendency for the thread to become clamped between the work and the horn, causing the thread to be stranded or other imperfections to result in the finished seam, particularly if the work is rigidly and unyieldingly clamped against the horn by the action of the presser foot and released only during work feed.

In the form of McKay sewing machine in which each stitch is set while the succeeding stitch is being formed, as in the two patents just referred to, a stitch setting tension is applied to the previously formed stitch while each needle loop is on the shuttle and is being passed over the locking thread case by the shuttle to form a new stitch. Thereafter, the take-up acts to draw the needle loop back toward the work from the shuttle. In order to avoid clamping the work rigidly and unyieldingly against the horn while each stitch is being set and thus to prevent any tendency for the thread to become clamped between the work and the horn, in this form of machine, it is the practice to relieve the compression of the work by the presser foot at least partially during the time in a sewing cycle while a stitch is being set by the shuttle and again while the take-up is drawing the needle loop back toward the work. Between these times, that is, while a stitch is being set and while a loop is being drawn from the shuttle, it is necessary to feed the work, the presser foot being lifted from the work during the feeding movement. The usual method of accomplishing the desired results in the operation of the presser foot for such machines, therefore, consists in providing a positively operating presser foot mechanism having an unyielding lock but including a yielding element which acts at the proper times to avoid rigid compression of the work.

As distinguished from this method of operation, the McKay type of machine disclosed in the patents to Topham and the present inventor, above referred to, is provided with a thread measuring finger in the work supporting horn which enables the threaded needle to be drawn through the work after the previously formed stitch is set without causing the thread to slide in the needle hook. In this way, each stitch may be set in the work during the same sewing cycle in which it is formed, the feeding movement taking place only after the stitch is set. A downward pull, therefore, is exerted on the work against the horn while the stitch is in alignment with the needle receiving opening, and no problem of abrasion or stranding of the thread arises from the thread being clamped between the work and the horn.

In the Topham machine, the stitch is set by the take-up acting to pull the work firmly against the work supporting surface of the horn so that it is feasible to set each stitch before feeding the work. After feeding the work, the presser foot may again be locked against the work for

substantially the entire remainder of a sewing cycle without danger of hindering any necessary movement of the thread between the work and the horn, the tightness of the seam being retained by the clamping action of the presser foot. In 5 order, however, to enable the compression on the work to be relieved somewhat while each needle loop is being carried over the locking thread case by the shuttle so that the compression of the work will not jam the thread within the needle perforation within which a stitch is being formed, the presser foot indicated at 95 of the present machine is unlocked while the shuttle is completing its loop carrying movement. This occurs in the machine illustrated herein just before the 10 stitch is set so that the presser foot 95 is unlocked briefly twice during each sewing cycle, once after a stitch is set in the work and once before the succeeding stitch is formed. The presser foot 95 is unlocked after the stitch is set to enable the presser foot to re-engage the work yieldingly after being fed, the presser foot mechanism being arranged to lift the presser foot positively from the work during feed as in prior machines.

Referring to Figs. 3, 4, 55, 56 and 62, the mechanism for actuating the presser foot to clamp and release the work is similar to that of inventor's prior patent, above identified, and comprises a presser foot bar, indicated at 96, located more nearly in alignment with the thread supporting surface at the end of the horn 4 than in the machine of the patent, so that a more direct force will be exerted on the work. The presser foot is clamped by a bolt 100 to an enlargement 98 at the lower end of the presser foot bar 96 which is mounted for vertical reciprocation in bearings 102 and 104 on the machine frame, the bearing 102 being formed with a cap secured by screws 106 to the frame. For actuating the presser foot bar, the bar has secured to it a collar 108 to which is pivotally connected a link 110 also connected to one arm of a lever 112 fulcrumed on a stud 114 in the machine frame. The other arm of the lever 112 is connected through a link 116 to a spring actuated lever 118 rotatable on the forward end of a horizontal shaft 120 rotatably mounted in the frame of the machine and surrounded by a torsional presser foot spring 122, best shown in Figs. 3 and 5, one end of which spring is fastened to a sleeve 124 adjustably clamped in the machine frame. The other end of the spring enters a notch 119 in the hub of lever 118 (see Fig. 55), the spring 122 acting to force the presser foot yieldingly against the work.

To lock the presser foot in engagement with the work and to unlock the presser foot so that a yielding pressure will be exerted on the work only at the proper times in each sewing cycle, the spring actuated lever 118 has pivotally connected to it by means of an enlarged headed screw 126 a substantially vertical curved link 128 also connected to a central pivot 130 on a double floating lever 132. One end of the floating lever is connected through a vertical link 134 to a cam actuated lever 136, the connection between the link 134 and the lever 136 being adjustable to enable the lifting movement of the presser foot to be varied. The other end of the floating lever has a pivot pin 138 passing through the movable portion of a lock, to be described further herein-after. The lock is so arranged that the connections, including the cam lever 136, link 134, floating lever 132, link 128, spring lever 118, link 116, lever 112 and link 110, will be rendered effective

or ineffective in causing the presser foot to be lifted when the cam lever moves. When the lock is unlocked, the spring 122 urges the presser foot bar 96 yieldingly toward the work support. When the cam lever 136 is held stationary with the connections through the lock effective, the presser foot is locked unyieldingly in engagement with the work. This is the condition of the presser foot mechanism while the needle penetrates and withdraws from the work. While the needle loop is being carried over the thread case by the shuttle and is being pulled down rapidly toward the work before a stitch is set, the lock is unlocked so that the compression of the work by the presser foot is relieved or at least exerted yieldingly, thus enabling the thread to pass in one direction or the other through the work easily without binding.

The presser foot lock is illustrated in Figs. 57 to 60, inclusive, and consists of a pair of wedge plates 140 and 142 and a central wedge member 144 having horizontal openings at their lower ends providing loose clearance spaces to receive the pin 138. The wedge plates and member are 20 slidingly mounted in a vertically arranged lock box 146 secured to the machine frame by means of screws 148. Between one of the wedge plates and the central wedge member is a spacing piece 150 and a vertical series of steel rolls 152 resting 25 at the lower end of the series against a locking finger 154 and compressed when the locking finger is raised against a stop pin 155 to cause the rolls to press the vertical wedge plates and spacing piece outwardly against each other and 30 against the sides of the lock box 146. When the locking finger is lowered, the rolls also are lowered and separated by gravity to unlock the lock. In other respects, the presser foot lock is substantially the same as that disclosed in United States 35 Letters Patent No. 2,056,670, granted October 6, 1936, upon an application filed in the names of 40 Joseph Gouldbourn et al.

The arrangement of the lock box vertically insures extremely rapid operation of the lock in 45 locking and unlocking the presser foot mechanism. If the guideway lock box is inclined or horizontal, the frictional component of each roll reacts on another of the series to render the unlocking action of the lock more sluggish than 50 when the guideway is exactly vertical. Each of the rolls 152, when the locking finger 154 is lowered, acts as an independent unit in separating one from the other to release the locking pressure of the wedge plates and member one from 55 another.

For actuating the locking finger 154, the finger is mounted on a horizontal shaft 156 rotatable in the lock box. The finger is releasably clamped for movement with an arm 157 pinned to the 60 shaft, and one end of the finger projects from the box and has secured to it an arm 158. The arm 158 is connected through a spring link 160 to an unlocking cam lever 162 having a roll 164 engaging a suitably shaped slot in a cam on the 65 sewing shaft 32. The link 160 is of tube-like formation within which is received a compression spring 166 acting at one end against a plug 168 and at the other end against a pin 170 mounted within slots in the side walls of the tube-like portion, the spring 166 tending to force the pin 170 to the outer extremities of the slots. The pin 170 forms the pivotal connection between the link 70 and the cam lever 162 which is bifurcated at one end to surround the slotted end of the link 160. By this construction, the spring 166 acts to hold

the locking finger in locking position at all times except when the cam lever 162 is moved to carry the pin 170 against the extremities of the slots in the link.

To unlock and actuate the presser foot out of engagement with the work manually, whenever required, there is rotatably supported at the forward end of the shaft 120 a hand lever 172 retained on the shaft by a screw 174 threaded into the end of the shaft and a washer 175 surrounding the screw. The lever 172 has at its rearward side a shoulder 176 arranged to be moved against an unlocking cam projection on a collar 178 rotatably mounted on the hub of the lever 172. When the lever 172 is moved manually in a counterclockwise direction, it rotates the collar 178, the cam projection of which raises a rod 180 slidably mounted at its lower end in a stationary lug 182 on the machine frame and pivoted at its upper end to an arm 184 clamped to the locking finger shaft 156, thus rotating the locking shaft to unlock the lock. Continued movement of the handle lever 172 in a counterclockwise direction brings a substantially horizontal arm of the lever 172 against a lug on the spring actuated lever 118, rotating the lever 118 and raising the presser foot through the connections including link 116, lever 112 and link 110. During return movement of the handle lever 172, the spring actuated lever 118 first causes the presser foot to be pressed against the work, and a spring 186, stretched between a pin on the projection of the collar 178 and a pin 188 on the stationary lug 182, returns the collar to its original position, permitting the rod 180 to be lowered and also the presser foot to be locked under the action of the spring link 160. For convenience in assembly, the spring actuated lever 118 is retained on the shaft 120 which supports the presser foot spring through a sleeve 190 pinned to the shaft 120 between an offset portion of the spring actuated lever and the handle lever 172. For actuating the lever 118 at the end of a sewing cycle to disengage the presser foot from the work automatically when the shaft 120 is rotated, the sleeve member 190 is formed with a finger 192 acting on a stud 194 projecting axially from the lever 118. The sleeve member also is provided with a finger 196 which serves as a limiting stop for the cam projection on the collar 178 when the collar is rotated by the spring 186. For stopping rotation of the shaft and the spring actuated lever 118 and preventing the presser foot from striking the work supporting surface of the horn, the under part of the spring actuated lever is provided with a lug 198 movable against a stud 200 in the machine frame.

As a convenient means for adjusting the operation of the presser foot lock, the releasing finger 154 is not secured directly to the shaft 156 but is adjustably connected to the arm 157 by a clamp screw 201. The arm 157 is pinned to the shaft and has an enlarged opening through which the screw 201 passes into threaded engagement with an opening in the finger, the arrangement being such that the relationship of the finger and shaft may be changed when the screw is loosened.

To sever the thread at the end of a seam while the work remains in position between the work support and the presser foot, the enlargement 98 at the lower end of the presser foot bar is grooved to form, with a cap plate 203 (see Fig. 62), an inclined guideway 202 for a thread cutter slide 204 movable toward and from the surface of the work. The slide 204 has cut along its upper edge a series

of rack teeth 206 engaging the teeth of a pinion 208 rotatable on a horizontal shaft 210 within the enlargement 98 of the presser foot bar 96. Also meshing with the teeth of the pinion at either side of the rack teeth 206 is a series of teeth 212 secured to the lower end of an actuating rod 214 within the tubular portion of the presser foot bar 96. The actuating rod 214 is reciprocated within the presser foot bar at the end of a seam before the presser foot is disengaged from the work by mechanism to be described.

The thread cutter consists of a knife 216 clamped within a lengthwise passageway of the slide 204 and formed at its lower end with an axial bore comprising a hollow tubular portion, the cutting edge of which is produced by grinding a flat surface across the knife at an acute angle to its length. The knife is so shaped and located that it engages the work in close proximity to the presser foot, forming an incision in the work and severing the threads beneath the surface of the work in a manner more fully described in United States Letters Patent No. 2,226,401, granted December 24, 1940, upon an application of Otto R. Haas.

In addition to the looper 6, the thread finger 8, the take-up 10, the thread tension 12, the curved awl 14 and the needle 18, the other stitch forming devices include a needle thread loop taker or shuttle 218 mounted to rotate about an axis disposed substantially 90 degrees to the needle 18 and at one side of the needle, a loop lifter 220, a loop spreader 222 and a pull-off device actuated during formation of each stitch to withdraw a measured length of locking thread from the supply. The stitch forming devices act to form and set each stitch during a single sewing cycle, the stitch being set by the take-up in the manner disclosed more fully in the patents to Topham and the present inventor. The stitches inserted in the work, indicated in Fig. 48 at 224, are of the usual lockstitch form composed of interengaging needle and locking threads 226 and 227 respectively, the points of engagement of which are pulled into the work uniformly during setting of each stitch.

As has been stated, an important feature of the invention relates to the locking thread measuring device which comprises gripping jaws 228, 230, best shown in Figs. 45 and 46, acting along the lead of the locking thread, passing from the thread case, indicated at 232 (Fig. 40) to the work, to withdraw locking thread from the supply in the thread case after each needle loop is pulled from the loop taker and to remain in gripping engagement with the thread while the stitch including the needle loop is being set in the work by the take-up 10. In order to insure that the proper amount of thread will be withdrawn during feed of the work by the awl, the gripping jaws are connected for actuation with the awl actuating mechanism. As the work is fed by the awl, the last formed stitch in the work is carried beneath the presser foot and is laid in engagement with the work by downward movement of the presser foot after the feed is completed. The gripping jaws, moving in unison with the feeding movement of the work, prevent the tension on the locking thread from interfering with the feeding movement or causing variation in the length of stitch. Thus, when the awl feeding movement is adjusted the length of locking thread pulled off will vary automatically in proportion to the change required by the adjustment.

Referring to Fig. 48, it will be apparent that a

substantial amount of locking thread is required to enable the thread to be laid along the surface of the work by the presser foot but not sufficient to complete the stitch inasmuch as the presser foot does not engage the work directly over the point of needle operation. Accordingly, the thread pulled off from the locking thread case by the gripping jaws is measured in an amount just short of the length of a stitch by the distance indicated at 234 which represents the spacing of the presser foot along the seam line from the point of needle operation. After the stitch is formed and as it is being set, a further amount of locking thread to complete the stitch is pulled off by the gripping jaws to supplement the amount pulled off during feeding of the work so that the locking thread is measured at two different times in a sewing cycle in amounts as required by the stitch forming operations without permitting the locking thread to become excessively slack. Since these operations occur uniformly in the same relation to the other stitch forming operations, a high degree of accuracy in the formation and location of completed stitches occurs in the work.

The locking thread gripping and measuring jaw 228, as shown in Figs. 45 and 46, is formed at the lower end of a hollow tubular slide 236 fitting within a circular guideway 238 formed on a race-way face plate member for the loop taker of shuttle 218, to be described further hereinafter. Mounted upon a transverse pin 242 passing through the slide 236 and within the slide is a lever 244 at the lower end of which is the jaw 230 and at the upper end of which is a lug having a threaded hole for connection with gripper actuating connections. To prevent rotation of the slide 236 within the guideway 238, the central portion of the lever 244 has a flange 246 which projects beyond the outer surface of the slide 236 and enters a lengthwise slot in the guideway 238. For actuating the gripping jaws to clamp and release the locking thread, the threaded hole at the upper end of the lever 244 carries a spherically headed stud 248 surrounded by a socket at one end of a link 250 the other end of which is provided with a similar socket surrounding the spherical head of a stud 252 carried by a cam lever 254. The cam lever 254 has an integrally formed gudgeon 256 rotatably mounted within an opening in an overhanging lug on the machine frame and, at its lower end close to the stud 252, is a cam roll 258 passing through an opening in the front wall of the machine frame into engagement with a slot in the front face of the cam 82 inside the frame, the cam slot being so shaped as to impart the proper thread clamping and releasing movements to the gripping jaw 230. To prevent entry of foreign materials through the opening in the frame for the cam roll 258, there is secured to the lever 254 between the lever and the cam roll a cover plate 260 having a sliding fit with the front surface of the machine frame.

The locking thread supply case 232 is provided with suitable thread guides and a tension for controlling and locating the thread in the proper position to be engaged by the gripping jaws 228 and 230, the thread case being retained within the shuttle 218 and held from rotation therewith by means to be described. The gripping and measuring jaws are actuated in each sewing cycle along the lead of the locking thread passing from the thread case to the work, to measure thread, and, after each stitch is set, the jaws release the thread and are disengaged therefrom in order to provide easy passage of the needle

loop about the thread case. To enable the gripping jaws to be disengaged from the locking thread passing from the thread case, the locking thread is led by its guides through a path at a slight angle to the path of movement of the jaws, as illustrated in Fig. 37. During each sewing cycle, the jaws are reciprocated from the solid-line position to the dot-dash line position. In the solid-line position, the jaws are disengaged from the thread, leaving a space for the passage of the needle loop between the jaws and their point of previous engagement with the thread. As the jaws are moved toward the dot-dash position, they approach and surround the thread to insure a firm grip. After the jaws grip the thread, the movement is continued in a downward direction to measure the amount required for a stitch. The measuring movement of the jaws occurs after the needle loop has passed between the jaws and their point of engagement with the thread and before and during the time of setting a stitch. The grip of the jaws on the thread is retained while the stitch is being set, to prevent variation in the amounts of thread measured as a result of the stitch setting tension. As soon as a stitch is set, the grip of the jaws is released and they are returned to their raised position clear of the locking thread. Thus, the jaws act to withdraw locking thread from the supply after each needle loop is pulled from the shuttle and remain in gripping engagement with the thread while the stitch including that needle loop is being set.

The mechanism for reciprocating the locking thread gripping jaws 228, 230 through their thread measuring movements includes the awl actuating and feeding mechanism. The upper end of the gripping jaw slide 236 is provided with a collar 262 having a socket for the ball-shaped lower end of a link 264 the upper end of which has a socket for a spherically headed pin 266 carried by one arm of an L-shaped lever 268. The L-shaped lever 268 is fulcrumed on an arm 270 formed integrally with a shaft 274 (see Fig. 44) passing loosely through a flanged circular disk 276 supported for rotation in the machine frame. Clamped to the shaft 274 at the opposite side of the disk from the arm 270 is an arm 278 pivotally connected with a link 280 which, in turn, is similarly connected to an arm 282 secured to the shaft 38 which supports the feed lever 36, the point of pivotal connection between the link 280 and the arm 282 being substantially concentric with the pivot 34 between the feed lever 36 and the link 24 forming the radius arm for the awl carrier (Fig. 51). By this arrangement, the same movement will be imparted to the locking thread measuring mechanism as is imparted to the awl during feed of the work. As has previously been noted, however, the connections are such that the thread which will be measured during work feed is somewhat less, by approximately one sixteenth of an inch, than the length of feed.

To supplement the measuring movement of the gripping jaws after the feed of the work has been completed, the second arm of the lever 268 is pivotally connected through a link 284 with a threaded bar 286 slidably mounted in a diametric passage of a block 288 secured to the forward end of the shaft 64 to which the link 58 is attached, rocking movement being imparted to the shaft by the link. The bar 286 is maintained in definite relation to the block 288 by a thumb 75 nut 290 engaging the threaded portion of the

bar and rotatably mounted within a recess, the walls of which engage either side of the thumb nut. By rotating the thumb nut 290, the effective length of the arm comprising the bar is changed and the thread measuring movement of the locking thread gripping jaws may be varied accordingly to change the depth in the work to which the take-up may draw the locking thread while setting each stitch. Since the measuring movement of the gripping jaws also is varied correspondingly whenever the feeding movement of the awl is changed, no adjustment of the thumb nut 290 will be required except when it is desired to change the depth in the work to which each stitch is set.

The supply of locking thread is supported within the thread case 232, the front end of which is open to receive a bobbin 292. For convenience in replenishing the supply of locking thread on the bobbin 292, the locking thread gripping jaws 228, 230, which act diametrically across the front of the loop taker or shuttle and thread case, are shiftable to render the thread case accessible for removal and replacement of the supply bobbin. To this end, the flanged disk 276 is provided with a laterally projecting handle portion 294 on which is pivotally mounted at 296 an unlocking lever 298 extending substantially parallel to the handle portion 294. To the inner end of the unlocking lever 298 is pivotally connected a spring pressed pin 300 arranged for entry in one position of the disk 276 into an opening in the machine frame. When the locking pin is received within its opening, the disk 276 is secured in the position of Fig. 43, the position of the fulcrum shaft 274 for the arm 270 being such that proper movements will be imparted to the gripping jaws for normal sewing operations. The fulcrum shaft 274, however, passes through the flanged disk 276 eccentrically of the bearing surfaces of the disk in the machine frame so that, when the locking pin 300 is withdrawn from its opening in the frame and the handle portion 294 of the disk is moved upwardly from the position of Fig. 43 to that of Fig. 47, the shaft 274 will also be moved bodily upwardly, causing the gripping jaws to be shifted away from the front of the thread case. In this position of the jaws, the bobbin 292 is readily accessible for replenishment.

The construction of the loop taker or shuttle 218 will be best understood in connection with Figs. 39 and 40. The main body of the shuttle comprises a hollow cylindrical body 302, provided with helically cut gear teeth about its outer surface. To the ends of the cylindrical body are secured an annular guide plate 304 and a similar backing plate 306, both having circular flanges fitting closely within the inner surface of the body 302. The thread case 232 has an integral collar portion projecting from its outer surface, the diameter of which collar portion fits the inner surface of the cylindrical body 302 of the shuttle. The width of the collar portion on the thread case is sufficient to hold it in position against endwise thrust within the shuttle when the guide and backing plates are secured to the shuttle body, the flanges on the plates engaging opposite sides of the collar on the thread case.

To receive the needle thread loop and carry it about the thread case, the guide plate 304 is notched radially to form a loop receiving hook 308 within the periphery of the guide plate, the throat of which hook is aligned with the forward end of a recess 310 between two adjacent teeth

70
75

inner surface of the hook 308 is inclined toward the center of the guide plate 304 and the periphery of the guide plate 304 is cut back along that portion facing the hook, to enable a portion of the needle thread to be moved into the path of the hook substantially in advance of the hook. The hook 308 on the shuttle is the first portion thereof to engage and enter the needle loop, the inner inclination of the hook acting to draw the thread in the loop radially into the throat formed by the hook. After the hook 308 enters the loop of needle thread, the shoulder formed by the surface of the tooth at the trailing side of the recess 310 spreads the loop as the shuttle rotates. The inclination of the helical teeth on the shuttle body is such that, during continued rotation of the shuttle, the needle thread is laid progressively along the shoulder bordering the trailing side of the recess 310 until it reaches the opposite end of the shuttle body from the guide plate 304. At the rearward end of the recess 310 opposite the hook 308 is a second needle loop receiving hook 312 projecting from the periphery of the backing plate 306, the backing plate being substantially of the same diameter as the outer edges of the teeth on the shuttle body except for the projecting hook 312. The throat of the hook 312 is aligned with the recess 310 but is displaced through an angle relatively to the throat of the hook 308 sufficiently to bring both throats into alignment with the recess. During further continued rotation of the shuttle, the loop is carried in a counterclockwise direction over the thread case; the shuttle also passing through the loop, the loop being moved downwardly at the opposite side of the thread case until it is free to be drawn toward the work by the take-up in the usual way. To secure the parts of the shuttle and thread case together, they are properly perforated and the backing plate is threaded to receive a series of assembly screws 314 (see Fig. 36).

The locking thread case 232 is constructed, in a manner similar to that heretofore employed successfully in many machines of the lockstitch type, with a circular thread supply receiving opening 316 having a slight eccentricity to the outer surface of the thread case and a central split spindle 318 provided to support the supply bobbin 292. The thread is led from the supply bobbin through a quick threading tension comprising a block member 320, slidable axially of the thread case, in a suitably formed guideway in the thicker portion of the circular side wall of the thread case. Along its central portion the block member has a notch to receive the free end of a curved leaf spring 322 secured within a slot in the collar portion of the thread case. The spring 322 forces an inclined end of the block member against the thread as it passes a grooved guide shoulder 324 in the thread case wall, after which the thread is carried diametrically across the front end of the thread case through a guide eye 325 in a triangular projection 326 on the thread case, the arrangement being such that the proper angular position will be given to the locking thread relatively to the path of movement of the jaws 228, 230 while measuring thread (Fig. 37).

The guide plate 304 of the shuttle is mounted for rotation within a raceway, illustrated in Figs. 36 and 38, having a backing plate 328 secured in fixed relation to the front wall of the ma-

chine frame by screws 330 threaded in the front wall. The backing plate has a semicircular groove 332 and a lug carrying a pivot 334 for a movable raceway member 336 mounted on the back pivot 334 to swing toward and from the backing plate radially of the raceway. The movable portion 336 has a raceway groove 338, one end of which is alined with the raceway groove 332 on the backing plate when moved against the backing plate, thus forming a substantially complete raceway fitting loosely and confining the periphery of the guide plate 304 of the shuttle. To close the front of the raceway and prevent endwise displacement of the shuttle therefrom, the outer face of the guide plate 304 is engaged by a face plate 340 formed with side flanges surrounding two sides of the backing plate and locking the movable portion 336 of the guideway to the fixed portion. The face plate 340 is hinged upon a pair of oppositely disposed screw studs 342 threaded in the backing plate 328, and the front corner edges of the backing plate and the movable raceway portion 336 are grooved to receive the flanges on the face plate. To clamp the parts securely together, a pair of screws 344 projects through openings in the face plate, the backing plate and movable raceway member, the screws being threaded in the front wall of the machine frame.

For driving the shuttle, the helical teeth on the shuttle body 302 mesh with corresponding teeth on a driving gear 346 secured to the forward end of a rearwardly inclined shuttle gear supporting shaft 348 rotatably mounted in fixed bearings 350 and 352, the axis of which is substantially parallel to the axis of the shuttle and is inclined but slightly to the main sewing shaft. The number of teeth on the driving gear 346 is the same as that on the shuttle, giving a 1-to-1 ratio.

To insure proper timed relation of the driving gear with the shuttle, the gear 346 has secured to its front face a disk 354 having a projecting tongue 356 fitting a radial notch 358 in the periphery of the shuttle guide plate 304. The machine is so arranged that the driving gear 346 normally will come to rest at the end of a seam with the tongue 356 on the disk 354 directly beneath the shaft 348 so that it will be possible to engage the shuttle with the driving gear only in a relationship in which the tongue enters the notch 358 in the guide plate. The shuttle shaft 348 is mounted at a slight inclination to the horizontal below the main sewing shaft 32 and is rotated through a train of gears from the main sewing shaft to impart three rotations to the shuttle shaft for each rotation of the main shaft.

The driving gear train for the shuttle shaft 348 is illustrated in Figs. 33, 34 and 35 and includes a driver 360 rotatable on the shaft 348 and a six-sided collar 362 mounted for sliding movement upon and splined to a sleeve 364 secured to the rearward end of the shaft. The collar 362 has an end face cam 366 fitting within a similarly shaped groove in the hub of the driver into which it is pressed yieldingly by a spring 368 coiled about the sleeve between the collar 362 and a pair of check nuts 370 on a hollow conical member 372 keyed to the shaft 348. The conical member fits within the sleeve 364 and forms a releasable retiming clutch between the shaft and the splined sleeve 364 while the cam and groove connection between the collar and the driver provides a slip joint for enabling the shaft 348 to be freed from the driver in case of jamming

in the shuttle or its driving gear. The driver 360 is cut with helical teeth meshing with corresponding teeth on one member of a double idler 374 disposed transversely to the driver and a gear 376 on the main sewing shaft meshes with the other member of the idler.

To prevent rotation of the thread case with the shuttle while at the same time enabling each needle loop to pass freely about the thread case, the shuttle shaft 348 is formed with a helical gear 378 at opposite sides of which are meshed two corresponding helical gears 380 secured to the upper ends of a pair of parallel nearly vertical shafts 382 disposed at right angles to the driving shaft 348. The shafts 382 are mounted in bearings in the machine frame and have at their lower ends a pair of substantially semicircular interrupted disks 384 (see Fig. 39) the outer edges of which enter slots 386 in the rear wall of the thread case. The disks 384 rotate together in the direction of the arrows in Fig. 39 in proper timed relation to engage the thread case one at a time to provide passage for the thread between the disks alternately.

The shuttle shaft 348 has, at its extreme ends, reduced threaded portions for a pair of clamp nuts 388 for taking up endwise looseness in the parts carried by the shaft and for securing the forward end of the shaft in the bearing 350.

For convenience in removing the bobbin, an injector is provided having a rack 387 (Fig. 34) mounted to slide in the frame of the machine with a reduced forward end in alinement with a suitable opening in the rear wall of the thread case. To reciprocate the bobbin ejector rack it is engaged by a gear segment 389 secured to a cross shaft 391 having a handle 393 at its outer end located outside the machine frame.

The loop lifter 220 is best shown in Figs. 26, 27 and 28. The thread engaging end of the lifter is pointed and of wedge shape to facilitate entry into the loop of thread carried by the needle and is grooved to enable it to surround the point of the needle after entering the loop so that the loop may be disengaged readily from the needle hook and lifted clear of the needle. The lifter is arranged to swing toward and from the needle and to overtake the needle in disengaging the thread from the needle hook. After the needle thread is disengaged from the needle hook, the movement of the lifter is retarded and the needle, continuing its movement away from the work, leaves the loop of needle thread wholly supported by the lifter.

For securing the lifter in position, the lifter has a right-angle shank entering a clamp at the end of a horizontal oscillating shaft 390 projecting from the front of the machine. The clamp for the loop lifter comprises a split eccentric bushing 392 within an opening 394 in the shaft, the bushing being compressed against the shank of the lifter by a cap screw 396 passing transversely through a pair of spaced lugs at the end of the lifter shaft.

The mechanism for actuating the thread lifter 220 includes an arm 398 at the rear end of the lifter shaft 390, a link 400 connecting the arm 398 with one arm of a lever 402 fulcrumed on the machine frame. The other arm of the lever 402 is connected through a link 404 to a pin 406 on a pitman 408 surrounding a crank 410 on the main sewing shaft 32. The pin 406 is located between the extreme ends of the pitman 408, the end opposite the crank 410 being pivotally connected at 412 with a radius arm 414 rotatable on a fixed shaft 416.

The loop spreader 222 acts to open the loop of needle thread in the path of the shuttle after the lifter 220 disengages the loop from the needle. In opening the needle loop in the path of the shuttle hook, the spreader is given a lateral and rearward movement first to enter the needle loop supported by the lifter and thereafter to draw one side of the loop rearwardly, as illustrated in Figs. 77 and 78. The speed of the rearward movement is so related to the rotary movement of the shuttle that, after laying the thread in the hook of the shuttle, it is laid accurately along the shoulder formed by the surface of the trailing helical gear tooth bordering the thread receiving recess 310 in the shuttle body. For this purpose, the loop spreader reciprocates toward and from the needle in a path at an angle to the helical teeth in the shuttle body across the lower outer surface of the shuttle. After being laid in the recess 310, the thread is engaged with the hook 312 on the backing plate 306, the spreader finally moving to the rear of the shuttle and holding the loop in spread position until the shuttle has lifted the loop clear of the spreader and lifter, as in Figs. 79 and 80.

The loop spreader 222 is constructed with a shank formed by a horizontal bar 418 shaped at its forward end with a hook, the point of which faces to the left of the machine (see Figs. 29 to 32 inclusive). The bar 418 is slidably mounted along its central portion in a hollow block 420 secured to a pivot 422 mounted for rotation in a fixed bearing and retained within the bearing by a collar 424 pinned to the upper end of the pivot. At its rearward end, the bar 418 surrounds a crank pin 426. The pin 426 is integrally and eccentrically connected to the under side of a planetary gear 428 to form a crank arm for the pin (see Fig. 31). The planetary gear 428 is rotatably mounted upon a stud 430 projecting from a rotating disk 432. Bolted to the under side of the disk is a casing 434 (Fig. 30) formed with a portion surrounding the hub of the gear 428 to prevent displacement of the gear from the stud 430. During operation of the machine, while the planetary gear 428 is rotated three times by the disk 432, it rotates about the stud 430 four times to carry the crank pin 426 through a cycloidal path having four lobes *a*, *b*, *c* and *d* of Fig. 32. The corresponding paths taken by the loop spreader 222 are distorted as a result of its sliding movement in the block 420 and its pivoting movement about the block to provide a continuous series of four lobate paths during each reciprocation of the needle, one of which paths intersects the loop of thread carried by the needle. These four lobate paths correspond to three rotations of the disk 432 and since the movement of the stud 430 about the center of rotation of the disk 432 is greater than the movement of the crank pin 426, the three rotations of the disk produce the principal forward and rearward movement of the loop spreader which occurs three times. The successive paths taken by the spreader are not congruent, each path being of slightly different shape from the previous one throughout the series. The path *c* of Fig. 29 has been selected as the one to enter the needle loop inasmuch as it is the one in which the spreader moves farthest forwardly. All the other paths lie behind the forward portion of the path *c* and are illustrated by arrows having reference letters corresponding to those of the diagram in Fig. 32.

For imparting cycloidal movement to the loop

spreader actuating crank pin 426 on the planetary gear 428, the disk 432 is fixed to the lower end of a vertical sleeve 436 rotatably mounted in bearings 438 in the machine frame. The upper end of the sleeve 436 has a splined connection with the hub of a helical gear 440 meshing with one portion of the double idler 314 which is driven from the gear 316 on the main sewing shaft. Rotation of the disk 432 moves the stud 430 in a circular path. The planetary gear 428 meshes with a sun gear 442 secured to the lower end of a vertical shaft 444 passing through the sleeve 436 and adjustably secured at its upper end by a clamp bolt 446 in the machine frame. As the planetary gear 428 is carried about the sun gear 442 by rotation of the disk 432, the planetary gear 428 is caused to rotate on the stud as well as to move bodily with it.

The rotary work supporting horn 4, the looper 6, the thread finger 8 and the take-up 10 are substantially the same as disclosed in inventor's Patent No. 2,159,166, the horn being mounted in friction reducing bearings 448 disposed on a vertical axis in alignment with the needle, as best shown in Figs. 14 and 16. The looper 6 consists of a sliding and rotating rod mounted in the upper inclined part of the horn and movable toward and from the tip of the horn to lay the thread in the hook of the needle. As the looper is moved away from the tip of the horn, it is rotated to engage the thread with the thread finger 8, and again to move toward the horn tip for measuring a sufficient length of thread between the looper and the last formed stitch in the work, to enable movement of the threaded needle hook through the work without imparting substantial tension to the thread. The amount of thread measured by the thread finger also is sufficient to insure that the thread lifter will enter and disengage the thread from the needle hook before the length of thread measured by the thread finger is exhausted. The principal advantage of such an arrangement is that there is no possibility of sliding movement of the thread in the needle hook at any time and, consequently, a relatively small sized needle may be employed for the size of thread utilized, the thread being compressed compactly into the throat of the needle hook during each operation of the looper. In this way, a relatively large size of thread may be drawn into a comparatively small perforation in the work, insuring the greatest possible efficiency in holding power of the finished seam as well as retaining the strength of the materials operated upon.

The shuttle in the present machine is somewhat larger in diameter than in the patented machine, and the take-up motion is modified accordingly, the take-up being mounted in the horn and actuated from a continuously rotating horizontal secondary shaft 450, also in the horn, similar to that of the patented machine. This secondary shaft also actuates the looper and thread finger (see Fig. 16) and is driven, through connections 65 with the main sewing shaft 32, in a manner similar to that in the machine of inventor's patent.

To facilitate proper engagement of the thread in the hook of the needle by the looper, in the illustrated machine, as the horn is rotated, a turning movement is imparted to the needle when it reaches a thread receiving position with relation to the looper. With the use of a rotating looper it has been found that a substantially smaller degree of turning movement is required in the needle than the amount of horn rotation

to enable the needle to receive the thread in its hook from the looper as the horn is turned about its vertical axis.

Referring to Figs. 20 to 25, inclusive, the mechanism for imparting the turning movement to the needle about its longitudinal axis with the horn as the horn is rotated is arranged to turn the needle through substantially a smaller number of degrees than the amount through which the horn is rotated. In order to insure uniform turning movement of the needle throughout the full range required, this mechanism is constructed to turn the needle proportionately with the rotation of the horn. For instance, if the horn is rotated from a given neutral position to a position 180° removed from the neutral position, the needle is turned through only 150°, the difference in rotation being taken up by the rotational movement of the looper in laying thread in the needle hook. If the horn is rotated 90° from the neutral position, then with a proportionate turning movement of the needle the needle is turned only 75°. Thus, the maximum difference between the degree of needle turning and the rotation of the horn within the range of the effective operation of the needle threading mechanism determines the ratio of the rotational movements between the needle and the horn.

The needle turning mechanism comprises a hollow needle supporting bar 452 mounted in vertically aligned bearings, one of which is indicated at 454 (see Fig. 17) in the machine frame. Near the upper end of the needle bar above a ball-shaped enlargement 456 is a splined portion of the bar fitting within a correspondingly machined tubular hub of a spur gear 458 (Fig. 20), which hub is rotatable in a fixed frame bearing at its lower end. The spur gear 458 is mounted in its bearings to restrain any vertical movement but to permit free rotary movement, reciprocation of the needle bar 452 while the needle is being actuated toward and from the work being taken up by the splined connection at the upper end of the needle bar. Thus, during the reciprocating stroke of the needle, the rotatable spur gear may remain stationary if not rotated.

In the machine of the prior patents, the upper end of the needle bar itself is formed with a series of elongated gear teeth meshing with a horizontal rack for rotating the needle bar. In order to provide a more rigid, lighter and more quickly responsive needle turning mechanism, the spur gear 458 of the present machine meshes with a gear segment 460 rotatable on a fixed vertical stud 462 entering the hub 464 of the segment secured in the machine frame, as illustrated in Figs. 5, 20 and 21. Projecting rearwardly from the hub 464 of the segment is a spherically headed pin 466 surrounded by a socket on a link 468 the other end of which is similarly connected to a pin 470 clamped to one end of a link 472 passing loosely through a second link 474, which links correspond to similar links in the needle turning mechanism of inventor's prior Patent No. 2,159,166. The link 474 is the adjusting link actuated through connections with the horn, to be described more fully hereinafter, and the links 468 and 472 form a toggle, the connecting joint of which is shifted by the adjusting link 474.

When no turning movement is imparted to the needle, the pin 470 forming the axis of pivotal connection between the links 468 and 472 lies substantially concentric to the arcuate movement of a pin 476 for actuating the needle turn-

ing mechanism. When the adjusting link 474 shifts the pin 470 out of concentricity with the arcuate movement of pin 476, oscillating movement is imparted to the link 472 to cause the link 468 and pin 466 to be shifted toward and from either extreme angular position, indicated by dot-dash lines in Fig. 21, depending upon whether the pin 470 is raised or lowered, Fig. 25 showing it raised.

For imparting arcuate movement to the pin 476, it is mounted in a horizontally extending arm of a divided needle rotating lever 478 (see Fig. 22). The lever 478 is fulcrumed on a pair of aligned, spaced pins 480 clamped in separated portions of the machine frame and formed with conical inner terminals fitting within conical bearing openings 482 in lugs at the sides of the lever. The lugs of the lever are spaced apart sufficiently to receive the pin 470 and the interconnected ends of the toggle and the adjusting links. When the lever 478 is oscillated on its fulcrum, the pin 476 is given an arcuate movement about the pins 480 in a substantially vertical direction toward and from alignment with the pin 466. If the pin 470 connecting all the links is held substantially in alignment with the axis of the fulcrum pins 480 (Figs. 23 and 24), no turning movement will be imparted to the needle but, if the pin 470 is shifted above (Fig. 25) or below the axis of the pins 480, then the needle turning movement will be in one direction or the other proportionate with the amount of shift.

The needle turning lever 478 is connected for actuation with the needle reciprocating mechanism through a link 484 one end of which surrounds the spherical head of pin 486 and the other end of which fits a similar head on a pin 487 in an arm 488 secured to a horizontal shaft 490 oscillated by the needle reciprocating mechanism, to be described hereinafter. The arrangement of the connections with the needle turning lever 478 is so constructed that substantially all of the turning movement is imparted to the needle when the needle reaches the lower end of its reciprocating stroke and while the hook of the needle is within the tip of the horn. When the needle is withdrawn from the work, it reaches a position with its point just above the loop lifter where there is no angular displacement of the needle hook, the needle loop always being located for easy reception of the loop lifter at the same relative angular position. As the needle completes the upper end of its reciprocating stroke, a slight turning movement is imparted thereto, but this turning movement has no effect on the handling of the thread inasmuch as the needle loop is freed from the needle before the upper end of the stroke is reached.

As shown in Fig. 17, the needle reciprocating mechanism includes the shaft 490 to which the arm 488 is secured, an arm 492 projecting outside the frame of the machine and having an integral connection with the shaft 490, and a link 493 having a spherical socket to fit the enlargement 456 on the needle bar, the joint between the link 493 and the enlargement 456 enabling the link to swing as the arm 492 is oscillated and the needle bar to rotate the required amount. To oscillate the shaft 490 and the arm 492, the inner end of the shaft has fixed thereto an upwardly extending arm 494 connected by a short link 496 to a radius arm 498 rotatable on a short shaft 500 fixed in the frame of the machine. Pivoted connected with the radius arm 498 by the same pivot which connects the link 496

is a link 502 connected with a pivot 504 at the upper end of the pitman 408 previously referred to as forming a part of the loop spreader actuating mechanism. The pitman 408 has a pair of pivots at its upper end including the pivot 504 and the pivot 412, the last mentioned pivot passing through and forming a connection with the radius arm 414. The pitman which is given its movement from the crank 410 thus causes the needle to be reciprocated toward and from the tip of the horn to penetrate the work and to withdraw a loop of needle thread during each reciprocation. To receive the needle during its downward stroke, the horn is constructed in the usual way with a needle opening 506 (see Fig. 16) in alignment with the axis of horn rotation.

To secure the needle 48 accurately in position in the needle bar 452, the lower end of the bar has a needle receiving chuck of ordinary construction formed by making a number of radial slots in the centrally bored lower end of the bar. The outside of the bar is threaded and is surrounded by a tapered chuck collar 508 acting when rotated to draw the tapered lower ends of the slotted portions on the bar tightly against the shank of the needle inserted therein. For locating the needle accurately in the chuck so that its lower end as it enters the needle opening in the horn will be positioned properly to cooperate with the needle looper, the upper end of the needle shank is brought into engagement with a stop pin 510 connected with a set screw 512 threaded in an enlargement of the central bore in the needle bar. Above the set screw 512 the needle bar is hollow throughout the remainder of its length to receive a suitable tool or screw driver for turning the set screw.

As in the machine of inventor's Patent No. 2,159,166, means are provided for securing the needle bar against rotation when the machine is brought to rest. In the patented machine, the rotation preventing means consists of a manually operated clamp, this clamp acting to prevent needle turning movement of the bar as a result of looseness in the connections of the needle turning mechanism, particularly when rotating the collar for the needle chuck. Securing the needle bar also facilitates disengaging and replacing the needle by preventing endwise movement of the needle bar. In some instances, it has been found that the machine may be started after the manually operated clamp has been set but not released. To avoid this difficulty, in the present machine, the means for securing the needle bar is actuated automatically by a driving and stopping mechanism both to clamp the bar in stopping and to release the bar when the machine again is started.

The needle bar clamp of the present machine consists of a split sleeve 514 of rectangular cross section forming a bushing for the bearing 454 and surrounding the needle bar. The sleeve 514 is secured at its upper end in the bearing 454 and, at its split lower end, the sleeve carries a rectangular clamp collar 516 provided with perforations to receive an eccentric pin 518 having one end attached to an arm 520. When the pin 518 is rotated, it engages one side of the split sleeve 514 and compresses it against the needle bar within the clamp collar, a set screw 522 being provided for adjusting the clamping operation. To rotate the eccentric pin 518, the arm 520 is connected through a link 524 to a pivot screw 526 threaded into an opening 528 on the sleeve 190 which is pinned to the presser foot spring supporting shaft 120 (see Figs. 4, 17, 19 and 54).

When the machine is brought to rest at the end of a seam, the shaft 120 is rotated to raise the presser foot from the work by the driving and stopping mechanism. This movement of the shaft causes the needle bar to be secured against rotation by the clamp 516 and, when the presser foot again is engaged with the work, the clamp is released.

The frame 19 of the machine is arranged to enclose substantially all the actuating mechanisms for the stitch forming devices so that continuous force feed and splash lubrication systems may be employed. In arranging the frame for easy access to the different mechanisms as well as to provide firm support for the main sewing and operating shafts, the frame is divided along the sewing shaft into separate compartments within which the different mechanisms are located, as illustrated in Fig. 5. Beginning at the front of the machine, just behind the front wall, is located the needle rotating mechanism and the driving gears for the shuttle and loop spreader. Behind these sets of mechanism is a partition 530 forming with the front wall of the frame a compartment 532. The needle reciprocating mechanism is located within a compartment 534 formed by the partition 530 and a partition 536. Behind the partition 536 is the awl reciprocating mechanism within a compartment 538 formed by the partition 536 and a partition 540, all the shafts and pivotal supports for the actuating parts being mounted in bearings in the partitions. By keeping the mechanisms separate in this way, relatively short connections are rendered possible and each separate mechanism may be treated independently when making repairs or adjustments without upsetting or requiring other mechanisms to be dismantled. Furthermore, the rockshafts which extend parallel to the main sewing shaft, for transferring motions produced by the mechanisms to the respective stitch forming devices, may be made as rigid as required without adding substantially to the weight of the operated parts. In addition to the mechanisms enumerated, a substantial proportion of the connections for imparting a feeding movement to the awl are accessible outside the front wall of the machine frame in order to enable the length of feed to be adjusted readily. Also, the associated locking thread pull-off connections with the feeding mechanism, particularly those pull-off connections which are adjustable, are located in the front of the machine outside the front wall.

The driving and stopping mechanism has for its main driving means high and intermediate speed clutches and a low-speed driving and braking clutch similar to those disclosed in inventor's prior Patent No. 2,332,649 granted October 26, 1943, and in inventor's application for United States Letters Patent Serial No. 506,319, filed October 15, 1943, patented July 30, 1946, No. 2,404,850. The main sewing shaft 32 has mounted upon it a pair of pulleys 542 and 544 (see Figs. 1, 5, 6 and 7) of different sizes carrying belts 546 and 548 surrounding high and intermediate speed pulleys 550 and 552, respectively, rotatable on an intermediate shaft 554. The intermediate shaft 554 is mounted in a bracket 556 secured at an intermediate position in the frame of the machine, the intermediate shaft being driven through a belt 558 from a motor 560 mounted on a fixed motor support 562. The intermediate shaft 554 drives the pulleys 550 or 552 through the action of a clutch disk 564 disposed between the pulleys 550 and 552 and arranged to engage selectively with either

Also mounted on the intermediate shaft 554 is a helical gear 566 meshing with a corresponding gear 568 secured to a shaft 570 disposed at right angles to the intermediate shaft and mounted in bearings in the machine frame with one end projecting through the frame and carrying a pulley 572. The pulley 572 is surrounded by a belt 574 for driving a pulley 576 on a cross shaft 578 comprising a portion of the low-speed driving and braking mechanism. On the cross shaft 578 is a worm 580 engaging a low-speed worm wheel 582 on the main sewing shaft 32. The worm wheel 582 has an inner conical clutch face cooperating with an outer clutch face on a movable clutch member 584 the hub of which is provided with a timing cam slot 586 engaged by a follower on a vibrating bell crank 588. One arm of the bell crank has a recess into which the upper end of a vertical lock bolt or controller pin 590 may enter to hold the bell crank stationary and cause the movable clutch member to be forced into engagement with the worm wheel 582 for a predetermined part of a rotation, thus reducing the speed of the sewing shaft and rotating the shaft at a lower speed and thereafter causing the shaft to be brought to rest with the stitch forming devices in predetermined stopping positions with the needle and awl disengaged from the work.

The high and intermediate speed driving clutches and the low-speed driving and braking clutch are controlled through treadle actuated connections similar to those disclosed in the patent and application last referred to. These treadle actuated connections, briefly, consist of a forked shifting lever 592 fulcrumed in the machine frame carrying a clutch collar 594 (see Fig. 6) surrounding the forward end of the intermediate shaft 554, a horizontal rod 596 (see Fig. 1) connected between the shifting lever 592 and a three-armed lever 598, and a vertical link 600 connected between one arm of the three-armed lever 598 and a control treadle fulcrumed at 602 in the base of the machine frame. Another arm of the three-armed lever 598 is connected through a vertical link 604 to a cam arm 606 pivotally mounted on a stud screw 608 (see Fig. 6). The cam arm 606 is engaged by a roll on an angle lever 610 connected to a rod 612 having in turn a connection with the lock bolt 590, the arrangement being such that, when the treadle is depressed, the lock bolt is withdrawn from the recess in the bell crank 588.

In the machine of the prior patents and application referred to, the stitch forming devices are brought to rest in position, disengaged from the work but just before the take-up reaches its full thread retracting position. On this account, the last formed stitch in the work does not have a full stitch setting tension applied thereto, so that the final loop of needle thread surrounding the locking thread is not drawn securely beneath the surface of the work. Also, the positions of the looper and thread finger in the horn are not in proper relation to give the best results in laying the loop of needle thread in the hook of the needle during the first stitch of a new seam when the machine is started. To avoid these difficulties as well as to cause the thread cutter to be thrown into operation, the presser foot to be raised from engagement with the work, and the tension released from the needle thread when the machine is brought to rest, the machine of the present invention is provided with mechanism controlled by the driving and stopping mechanism for imparting the necessary movements to the stitch form-

ing devices and the thread cutter. When the machine is restarted the stitch forming devices are again restored to their sewing relationships.

In the illustrated machine as in the machine of the patents, the take-up, looper and thread finger are mounted in the rotary work supporting horn 4 and are actuated by the secondary shaft 450 in the horn (Fig. 16). To prevent rotation of the horn about its bearings from changing the angular position of the secondary shaft 450, a differential set of gearing is provided, comprising a helical gear wheel 614 secured to the shaft 450, meshing with a gear 616 at the upper end of a hub rotatably mounted on a vertical shaft 618 rotatable in a bearing in the horn. The lower end of the hub of the gear 616 is provided with internal teeth 620 meshing with a planetary gear 622 rotatable on a stud 624 eccentrically mounted on a spur gear 626. The gear 626 is rotatable about the shaft 618 and engages a similar gear 628 at the upper end of a hollow vertical horn transmission shaft 630 mounted for rotation concentrically with the rotary axis of the horn. The planetary gear 622 also meshes with a sun gear 632 on the shaft 618, and the shaft 618 has at its lower end a second gear 634 meshing with a ring gear 636 normally held in stationary position during sewing operations.

The driving connections between the horn transmission 630 and the sewing shaft 32 are shown in Figs. 1, 6 and 14 and comprise a bevel gear 633 at the lower end of the transmission shaft meshing with a bevel gear 635 at the lower end of a shaft 637 inclined at an angle of substantially less than 90° to the transmission shaft. The shaft 637 drives the parts in the horn including the looper. The upper end of the inclined shaft has a driven bevel gear 639 meshing with a bevel gear 641 on the sewing shaft 32.

To cause the take-up to draw the final stitch of a seam securely beneath the surface of the work, the ring gear 636 is given a predetermined angular movement when the machine is brought to rest and, to impart this movement, the ring gear is rotatable on a sleeve portion 447 of the machine frame (see Figs. 14 and 15) formed internally to provide a support for the upper bearing 448 and at its lower end with helical gear teeth 638 fitting a circular recess surrounding the sleeve portion 447 through which the lower spindle portion of the horn passes. To hold the ring gear 636 in proper axial position, the upper surface of a shoulder above the gear teeth 638 is engaged by a confining plate 640 clamped to the machine frame. The gear teeth 638 mesh with similar teeth on an idler 642 rotatable on a fixed vertical stud 644 and arranged to mesh with a second idler 646 on a fixed vertical stud 648. The idler 646 meshes with a gear 650 rotatable on a horizontal sleeve 652 bolted to the machine frame (see Fig. 15).

To rotate the gear 650, the hub of the gear is connected with a sprocket 654, also rotatable on the sleeve 652 and engaged by an endless chain 656. The chain 656 also engages a sprocket 658 (Fig. 7) secured to an intermittently rotated horizontal auxiliary shaft 660. The ends of the shaft 660 are supported in suitable bearings in the machine frame and at one end the shaft 660 has a driven member 662 of an auxiliary two-position clutch, the driving member 664 of which is in the form of a gear rotatable on the shaft 660.

The driving member or gear 664 of the auxiliary two-position clutch engages a pinion 653 carried by the continually rotating low speed cross shaft

578 and has riveted to one face an internally notched collar 666 surrounding a reduced hub of the driven clutch member 662 (see Figs. 11 to 13). Cooperating with the notches in the collar 666, there is rotatably mounted in the driven clutch member 662 a stud 668 having a diametric cut in one end within the collar to clear the collar with the stud in one position. When the stud 668 is rotated to disengage the collar 666, as in Fig. 13, the driving connection between the gear 664 and the driven clutch member is discontinued. If the stud 668 is rotated from this position, it is engaged immediately by a portion of the collar 666 between the notches, establishing a driving connection between the parts of the clutch.

To enable the driven member of the auxiliary clutch to be stopped in either of two positions, the stud 668 has a radial projection at the end opposite the diametrical cut arranged to engage either of two shiftable cylindrical abutments 670 and 672 slidably mounted in the machine frame in suitably spaced angular relation to the auxiliary shaft 660 to give the desired rotation to the shaft between stopping positions. The abutments 670 and 672 are pivotally connected for alternate movement into the path of the projection on the stud 668 through a lever 674 fulcrumed on a pivot 676 secured in a lug outside the machine frame. When the projection on the stud 668 engages the abutment 670 the auxiliary shaft 660 has just completed the auxiliary seam, terminating operations, and when the abutment 672 is effective the parts are returned to proper relative sewing positions.

To actuate the abutments 670 and 672 for bringing the two-position shaft 660 into either its seam terminating or sewing position, the lever 674 is connected through a horizontal link 678 to the lower arm of a lever 680 fulcrumed on a fixed pivot 682, best shown in Figs. 7 and 12. The upper arm of the lever 680 has pivotally mounted on it a pawl 684, the free end of which is movable vertically toward and from a shoulder 686 on a spring pressed carrier 688 in which the lock bolt 590 for the low-speed driving and braking mechanism is slidably mounted. The lock bolt carrier 688 is acted upon by a compression spring 690 retained within a recess of the machine frame in such a way that, after the lock bolt 590 engages the recess in the vibrating bell crank 588, the carrier 688 is given a short reciprocating movement, thereby enabling the pawl 684 to rise and imparting motion through endwise movement of the pawl to disengage the abutment 670 from the projection on the stud 668 and to move the abutment 672 into the path of the projection. When this movement occurs, a tension spring 692, stretched between an eccentrically mounted pin on the stud 668 and a pin on the movable clutch member 662, rotates the stud 668 toward clutch-engaging position, causing the shaft to be rotated a part of a complete turn until the abutment 672 is reached.

To prevent reverse rotation of the driven clutch member under the influence of the spring 692 acting through the projection on stud 668 and against the abutment 670 or 672, the driven clutch member has a pair of notches 694 and 696 disposed in the same angular relation as the abutments about the shaft 660. In either stopping position of the driven clutch member 662, one of the notches is engaged by a spring actuated detent 698 rotatable on a fixed pin 700.

The pawl 684 is retained yieldingly in position with its free end in contact with the shoulder 686

on the lock bolt carrier by a tension spring 702 connected at its ends to the pawl and to the lock bolt carrier. The pawl therefore connects the lock bolt carrier with the auxiliary clutch. This is the relationship of the pawl and the lock bolt carrier after the machine has been brought to rest and the final stitch of a seam completed. In rotating the two-position clutch toward the position of Figs. 7 and 13, the connections just described cause the ring gear 636 and the secondary shaft 450 to turn through a partial rotation sufficient to move the take-up 10 to its full thread retracting position.

In starting a seam for a new sewing operation, 15 the pawl 684 disconnects the lock bolt carrier from the auxiliary clutch, being disengaged from the shoulder 686 on the lock bolt carrier by a lug 704 projecting from the lock bolt or the controller pin 590. When the control treadle is depressed, 20 the lug 704 presses the pawl downwardly while the lock bolt 590 is being disengaged from the vibrating lever 588. As soon as this occurs, the lever 680 has its upper end actuated by a spring pressed plunger 706 slidably mounted in the machine frame to cause the abutment 670 to be withdrawn from engagement with the projection on the stud 668, and the abutment 672 moved into the path of the stud projection, thus engaging the clutch for limited rotation. Engagement of the 25 clutch 662, 664 causes the shaft and other connections between the clutch and the secondary shaft 450 to be rotated, restoring the proper timed relationship between the take-up and the other stitch forming devices for effective regular sewing operations.

The mechanism for actuating the thread cutter is illustrated in Fig. 61 and includes the rod 214 within the presser foot bar 96, a block 708 slidably received in the upper end of the presser foot bar 40 and connected with the upper end of the rod 214, a link 710 connecting the block with an arm 712 fixed to a stud 714 rotatable in a fixture 716 clamped to the upper end of the presser foot bar, an arm 718 also fixed to the stud 714 and forming with the stud 714 and arm 712 a bell crank, a link 720 extending at right angles to the presser foot bar connected between the arm 718 and an arm 722 secured to one end of a shaft 724 rotatably mounted in bearings above the partition 540 50 of the machine frame (see Fig. 5). The arrangement of the link 720 at right angles to the presser foot bar enables the presser foot bar to be reciprocated toward and from the work without substantially changing the position of the thread cutter in the presser foot bar, the link being relatively long as compared to the vertical movement of the presser foot bar. The shaft 724 is surrounded by a thread cutter actuating spring 726 one end of which engages a bushing 727 clamped in one of the bearings for the shaft and the other end of which is hooked about the arm 722, the spring 726 urging the connections to move the thread cutter into engagement with the work. To hold the thread cutter out of engagement with the work and to cause it to act at the proper time after the needle and awl have been disengaged from the work and the take-up moved to its stitch setting position, the shaft 724 has integrally joined to one end of it an arm 728 connected through a vertical link 730 to one arm of a three-armed lever 732 fulcrumed on a fixed shaft 734 on the machine frame. Another arm of the lever 732 acts as a follower for an open cam 736 having a recess 738 within which the follower 75 arm of the lever 732 may drop under the force

of the spring 726. The cam 736 is secured to the auxiliary two-position shaft 660 which is given a partial rotation when the machine is brought to rest, the arrangement being such that the recess 738 moves into line with the follower arm of the lever 732 before the presser foot is disengaged from the work. To prevent excessive impact while actuating the thread cutter, the arm 722 is provided with a pad 739 arranged to engage a finished surface on the machine frame when the thread cutter is actuated. The thread cutter is thus actuated while the work is securely clamped in position by the presser foot and immediately retracted by the cam 736.

To disengage the presser foot from the work automatically at the end of a seam, the presser foot spring supporting shaft 120 and the sleeve 190 fast to the shaft are given a partial rotation, bringing the finger 192 on the sleeve 190 against the stud 194 on the lever 118 and rocking the lever to raise the presser foot from the work. Since the machine comes to rest with the presser foot lock unlocked, the presser foot may be raised freely at this time.

To rotate the presser foot spring supporting shaft 120, the rearward end of the shaft has connected to it an arm 740 (see Figs. 5 and 7). The arm 740 is connected through a link 742 to one arm of a cam lever 744 rotatable upon a fixed stud 746. The other arm of the lever 744 has a roll engaging a slot in a cam 748 secured to the two-position auxiliary shaft 660. When the auxiliary shaft is turned to stopping position, the cam lever 744 is shifted, being offset in the track of the cam 748 to rotate the spring supporting shaft 120 and disengage the presser foot from the work. When the auxiliary shaft is turned to sewing position, the cam lever 744 is shifted to return the presser foot into engagement with the work.

Referring to Figs. 14 and 15, the variable sewing thread tension 12 consists of a shouldered rod slidably mounted in lugs 750, 751 of the machine frame below the lower end of the hollow vertical shaft 630 for driving the mechanism within the horn so that the thread engaging the tension may pass over the tension, downwardly into a wax pot (not shown) and upwardly through the hollow shaft 630. The thread engaging the shouldered portion of the thread tension rod 12 is compressed against a washer 752 backed by the lug 750 and notched to receive a pin 654 carried by said lug and engaged with a similar notch in the shouldered portion of the rod. Compression of the shouldered portion against the thread is imparted by a spring 756 coiled around the opposite end of the rod between the other lug 751 and a check nut 758 threaded on the rod.

To relieve the tension on the thread during sewing and at the end of the seam, an adjustable set screw 760 threaded in the end of the thread tension rod 12 is engaged by an arm 762 secured to the lower end of an inclined shaft 764 rotatable in the machine frame. The upper end of the shaft 764 has attached to it an arm 766 provided with a surface engaged by an arm 769 actuated by a cam 771 on the shaft 637 and by one arm of a lever 768 rotatable on a fixed pivot 770. The cam 771 acts to relieve the tension on the thread while the thread is being engaged with the thread finger 8 (see "Thread tension," Fig. 63). The other arm of the lever 768 is pivotally connected with a rod 772 clamped within an eccentric strap 774 surrounding an eccentric on the hub of the gear 650. When the gear 650 75

6

is given a partial rotation at the end of the seam after the thread cutter has been actuated and while the presser foot is being disengaged from the work, the eccentric strap causes the tension to be relieved.

While the stitch setting tension remains on the thread at the end of a seam, the auxiliary mechanism, including the two-position clutch and shaft, acts to cause the looper to lay the thread in the thread finger preparatory to a new sewing operation. After the thread is laid in the thread finger, the looper is advanced relatively to the thread finger to cause the thread engaged thereby to be trapped between the thread finger and the looper. In this way, improper looping action is avoided when starting a new seam. Rotation of the secondary shaft 450 in the horn while moving the take-up to stitch setting position also acts through the connections with the thread finger and looper to bring about this operation, the connections between the secondary shaft and the thread finger and looper being the same as disclosed in inventor's Patent No. 2,159,166.

It is apparent that the set of differential gears, composed of gear members 616, 626 and 634, are so arranged that the driving and stopping mechanism acts through the auxiliary mechanism connected to the third member 634 of the differential gear set to advance the secondary shaft 450 beyond the point to which it is driven at the end of a sewing operation. This advance of the secondary shaft causes the auxiliary operations, above referred to, to be brought about and the final stitch of the seam to be firmly set in the work. The auxiliary mechanism is set in operation by the driving and stopping mechanism, and the timing is so arranged that the stitch is set, the thread laid in the thread finger, the thread cutter actuated, and the tension relieved after the main sewing shaft has been stopped, substantially in the order noted.

Frequently during operation upon a shoe, it may be desirable to stop the machine before the operations are completed. In order to avoid the possibility of severing the threads and forming an incision in the sole at the forepart of the shoe being operated upon, the present machine is provided with connections actuated by the horn to render the thread cutter inoperative except while the horn assumes a predetermined position to which it must be turned in completing the seam. Thus, operation of the thread cutter is prevented and unnecessary injury to the sole of the shoe is avoided.

The connections for preventing operation of the thread cutter comprise a downwardly extending arm of the three-armed lever 732 (Fig. 61), a latch 776 secured to a shaft 778 rotatable in the machine frame, and an arm 780 also secured to the shaft and connected through a vertical link 782 with one arm of a horizontal lever 784 fulcrumed on a pin 786 secured in the side wall of the machine frame. The other arm of the lever 784 carries a roll 788 engaging a slot 790 in a cam block 792 rotatable on but maintained in predetermined angular relation with a spindle portion 794 of the work supporting horn 4 (see Fig. 14). As illustrated more particularly in Fig. 76 of the drawings, the shoe is supported on the horn with the bend in the horn extending to the left both at the time when a new operation is started and at the time the sewing is completed. When the horn is in this position, a rise in the cam slot 790 causes the

latch 776 to be held out of the path of the adjacent arm of the three-armed lever 732. With the horn in other angular positions assumed while operating along the forepart of the shoe, the cam roll 788 is lowered and the latch 776 is moved into the path of the adjacent arm of the lever 732, thus locking the lever out of operation and preventing actuation of the thread cutter.

For convenience in construction, the cam block 792 also is formed with a helical surface 796 engaged by one arm of a follower lever 798 comprising a part of the connections for actuating the adjusting link 474 of the needle turning mechanism. The lever 798 is fulcrumed on a fixed pin 800, and the other arm of the lever has connected to it a tension spring 802 stretched between the lever and the machine frame and also has connected to it the lower end of a rod 804, the upper end of which is connected to an arm 806 in the sewing head of the machine, as shown in Figs. 5 and 20.

The arm 806 is pivotally mounted on one end of a fixed stud screw 808 and has a pivot 810 for a link 812 pivotally connected at 814 to an arm 816 on an adjusting shaft 818 rotatable in a bracket 820 bolted to the machine frame. The adjusting shaft 818 extends above and substantially parallel to the main sewing shaft 32 and has fixed to its forward end an arm 822 pivotally connected with the adjusting link 474 of the needle turning mechanism. The central part of the adjusting shaft 818 carries a coil spring 823, one end of which is connected to the machine frame and the other to the shaft, thus assisting the spring 802 in the operation of the connections.

The shape of the cam surface 796 (Fig. 14) includes an abrupt shoulder between the high and low portions of the surface and, to avoid the possibility of sudden fluctuation in adjustment of the needle turning mechanism while the needle is being looped, the adjusting shaft 818 is locked during certain portions of each sewing cycle by a pair of ratchet wheels 824 and 826, having teeth facing in opposite directions, secured to the adjusting shaft and a pair of pawls 828 and 830 engaging the respective wheels (see Figs. 5, 8 and 9). The pawls 828 and 830 are rotatably mounted on a fixed pivot 831 and are pressed into engagement with the wheels by individual springs 832. The springs 832 are coiled about a pin 834 projecting from a plate-like offset portion of the bracket 820 above the fixed pivot 831.

To disengage the pawls 828 and 830 from their ratchet wheels at the proper time in each sewing cycle, the pivot 831 has rotatably supported thereon between the pawls 828 and 830, a plate 836 carrying a pin 838 forming a pivotal connection with a link 840 also connected with a cam arm 842 actuated by a track in a cam 844. The arm 842 is rotatable on the other end of the screw 808 which is secured in a bearing block 848 clamped to the frame of the machine, the other end of the screw serving as a pivot for the arm 806. The pin 838 extends laterally over the tail portions (Fig. 8) of the pawls 828 and 830 so that, when the pin is lowered, it raises the pawls from engagement with their respective ratchet wheels. This occurs when the needle is at the upper end of its stroke, the wheels being locked while the needle is in looping position so that sudden changes in the turning position of the

needle will not occur while the needle is within the needle opening in the horn.

To turn the needle into a position at the upper end of its stroke which will facilitate shedding of the needle loop as the loop is engaged with the shuttle, the arm 806 which forms a part of the adjusting connections for the needle turning mechanism has a slot 850 into which projects a pin 852 carried at one side of a second cam arm 854 rotatable on the stud screw 808 close to the arm 806. The arm 854 has at its free end a cam roll 856 engaging a track in the cam 844 at the side opposite to the arm 842. The timing of the cam arms 842 and 854 is such that, after the arm 842 is lowered to disengage the pawls 828 and 830 from the ratchet wheels, the arm 854 is lowered to depress the arm 806 and hold it in lowered position while the needle is at the upper end of its reciprocating stroke. Depression of the arm 806 causes the needle turning mechanism to turn the needle slightly, carrying the needle hook rearwardly while the loop of thread drawn through the work is being shed from the needle hook and is being taken up by the shuttle. By turning the needle hook rearwardly there is less opportunity for the thread to become stranded on the needle, and an easier movement of the needle loop about the shuttle is insured.

In the time chart of Fig. 63, the relative positions of the horn 4 and the needle 18 are illustrated in plan outline, the needle being indicated in section taken through the throat of the hook, to indicate the angular position of the hook by the unsectioned portion. The needle turning mechanism imparts a turning movement to the needle to the positions indicated or proportionately to the rotary movements of the horn, either counterclockwise or clockwise, as indicated by the full and dotted lines from a neutral or horn focus position in which no turning movement of the needle occurs, represented by the dot-dash line. In the loop lifting and spreading position of the needle while the needle is at the upper end of its reciprocating stroke, the angular position of the needle is always the same and coincides with the solid line of the chart. The other stitch forming devices and actuating members are given movements in the degree and direction indicated by the different curves identified by their descriptive titles. The titles "Lever lift" and "Lever lock," respectively, refer to the lifting movements imparted to the follower lever 798 by the rotation of the adjusting shaft 818 and the locking action on the lever by the engagement of the pawls 828 and 830 on the ratchet wheel 826 at the end of shaft 818.

The sewing operations occur between zero and 360° rotation of the main sewing crank shaft 32, the consecutive degree positions of which are indicated at the top of the chart. At the bottom of the chart, are other degree indications from zero to 360° in addition to and adjoining both ends of the crank shaft rotation portion of the chart. The additional degree indications correspond to the rotation of the auxiliary two-position shaft 660.

Before the sewing operations are started on a new seam, the auxiliary shaft 660 is given a 260° rotation to bring the stitch forming devices into proper timed relationship and to cause the presser foot to be lowered against the surface of the work on the horn. At the end of the operation the stitch is set by the take-up, the thread is severed by the cutter, the looper and thread finger are moved relatively to trap a length

of thread between them, and the presser foot is disengaged from the work in the order stated. These operations are accomplished by the final rotation of the auxiliary shaft between 260° and 360°.

It will be noted that the characteristic of "thread measuring" has two distinct active measuring portions between the 20° and 40° positions in which different amounts of locking thread are drawn from the thread case. These measuring portions are separated by an inactive section corresponding to a dwell in the movement of the grippers while grasping the locking thread. During the dwell in the movement of the grippers, the stitch is being set by a pull imparted to the needle thread acting against the locking thread which is held immovable in the grippers. The first active portion of the "thread measuring" characteristic is to provide sufficient locking thread for drawing the point of engagement between the needle and locking threads to a uniform depth below the surface of the work. The second active portion of the "thread measuring" characteristic corresponds with the feeding movement of the work and provides locking thread, as previously explained, to enable the locking thread to be drawn along the surface of the work beneath the presser foot during feed of the work.

The embodiments of the locking thread measuring grippers illustrated in Figs. 64 to 72, inclusive, causes substantially the same movements to be imparted to the grippers as in the embodiment first described except that greater reciprocating movement is imparted to the grippers while moving upwardly to clear the thread case and render the thread case free of obstruction by the grippers. The movements of the thread measuring grippers at different times in the rotation of the main sewing crank shaft both to open and closed positions and in the lengthwise reciprocating thread measuring positions are illustrated in the time chart of Fig. 66. The uppermost position of the grippers is substantially higher than in the embodiment of the mechanism first described.

To impart higher upward movement to the thread measuring grippers in the second embodiment of the gripper actuating mechanism of the present invention, three separate actuating mechanisms are provided, one of which moves the jaws while gripping the locking thread through a fixed distance to cause the locking thread to be drawn to a uniform depth in the work, another of which moves the jaws while gripping the thread through a variable distance depending upon the length of each stitch, and a third of which causes the jaws to be shifted to render the thread case free of obstruction. In Fig. 64, the jaws are shown substantially in stopping position of the machine. When moved to fully retracted position, as illustrated in Fig. 71, the thread case is free of obstruction, the jaws being disengaged from the thread and substantially out of range of the open side of the thread case. When actuated to grip the thread and moved to extreme thread measuring position, as in Fig. 69, the jaws are in their lowermost position. The construction of the gripping jaws and the mechanism for opening and closing the jaws are the same as previously described, and the same part numbers are employed. Also, the main sewing shaft 32 and the same portions of the crank driven awl actuating mechanism are utilized to impart movement to the jaws but the connections are arranged to provide a differently

timed mechanism. In the embodiment of Figs. 64 to 72 the awl mechanism is connected to move the jaws free of the thread case and a second cam actuated mechanism has been added to move the jaws through a fixed distance to cause the stitch to be drawn to a uniform depth in the work. The mechanism for providing locking thread corresponding to the work feeding movement remains substantially the same and is operative between the times of operation of the added, second cam mechanism and the operation of the awl mechanism in moving the jaws.

The mechanism for shifting the jaws free of the thread case to enable unobstructed passage of the needle loop by the shuttle and for other obvious purposes includes a link 858 the lower end of which is ball shaped and is received within the socket on the collar 262 of the gripping jaw slide 236, as in the first described form of the mechanism. The upper end of the link 858, in turn, has a socket for a spherically headed pin 860 in one arm of a lever 862 fulcrumed on an arm 864 formed integrally with a shaft 866 (see Fig. 65) passing loosely through a flanged disk 868 supported for rotation in the machine frame. The lever 862 has connected to its other arm a link 870 also connected to an arm 872 clamped to a lug projecting from the hub of a link 874 secured to the shaft 64, previously described, rotatable in bearings in the machine frame. The link 874 is actuated by the pitman 60 mounted on the crank 62 on the main sewing shaft 32.

The mechanism for moving the jaws through a distance varying with the length of each stitch comprises the shaft 866 to which is clamped, at the opposite side of the disk from the arm 864, an arm 876 pivotally connected with a link 878. The link 878 is connected to an arm 880 secured to the shaft 38 which supports a feed lever 882 corresponding substantially to the feed lever 36 previously described, but of slightly different shape. The feed lever 882 has a cylindrical guideway within which slides a bar 884 pivotally connected at 886 directly with a dovetail slide 888, substantially the same as the slide 72, adjustably clamped in a calibrated guideway 890 at the outer end of a stud 892 rotatable in the machine frame. The stud 892, together with an arm 894, forms a lever carrying a cam roll 896 engaging the track cut in the cam 82 on the sewing shaft 32, as previously referred to.

The second cam mechanism, added in the embodiment of Figs. 64 to 72 for moving the jaws while gripping the thread through a fixed distance to cause each stitch to be drawn to a uniform depth, acts upon the disk 868 and consists of a link 898 pivotally connected at one end to a lateral projection on the disk 868 and carrying at its other end a pivot comprising a clamp bolt 900 adjustably secured within a slot 902 in a calibrated arm of a lever 904 having an integral fulcrum stud 906 rotatable in the front wall of the machine frame. The stud 906 projects through the machine frame, and the other arm of the lever located inside the front wall is provided with a cam roll 908 engaging the same cam track of the cam 82 as the cam roll 896. The two cam rolls 896 and 908 are displaced in angular relation about the axis of the cam 82 to cause the rolls to be moved in sequence, the roll 908 being moved during each sewing cycle after the cam roll 896. After the cam rolls 896 and 908 are active, the gripper jaws are actuated by the crank 62 of the awl actuating mechanism to shift them clear of the thread case.

To adjust the uniform depth to which each stitch is drawn beneath the surface of the work in the modified embodiment of this feature, the clamp bolt 900 is loosened and moved along the slot 902. Movement of the bolt 900 changes the shifting movement of the thread measuring grippers while the grippers are disengaged from the thread, and, also, the position to which the grippers are moved before the jaws engage and grip the thread. Thus, the extent of movement of the jaws after gripping the thread may be regulated to suit the qualities of the work operated upon.

The gripper jaw shifting mechanism comprising connections with the awl actuating mechanism is effective to carry the jaws away from the front of the thread case during a period in each sewing cycle between 200° and 300° of rotation of the main sewing shaft 32 from stopping position, as indicated in Fig. 66. In order to avoid the necessity for rotating the sewing shaft manually to render the thread supply bobbin accessible for removal or replacement, the connection between the arm 872 and the link 874 is arranged to be quickly disconnected. To this end, the arm 872 has a transverse passage through which passes a wing bolt 912 having its threaded end movable into engagement with a threaded opening in the lug portion of the link 874. When the wing bolt is inserted in the threaded lug portion of the link 874 and tightened, the arm 872 and the link 874 form a rigid lever to impart the proper movement to the gripper jaws, as in Figs. 64, 69 and 71. If it is desired to shift the gripper jaws clear of the thread case when the machine is in stopped position, the wing bolt 912 is unthreaded from the lug portion of the link 874, disconnecting the arm 872 and the link 874, as in Fig. 67. To return the wing bolt in the arm 872 when disconnected from the link 874, the arm has an enlarged recess for the bolt within which is received a nut 913 threaded on the bolt (Fig. 72).

In conjunction with the modified form of thread measuring gripper jaw actuating mechanism of Figs. 64 to 72, inclusive, a modified form of awl actuating and feeding mechanism is provided. The modified form of awl actuating and feeding mechanism is best shown in Figs. 73, 74 and 75, in which the cam roll 896 on the arm 894 imparts movement to the calibrated guideway 890 and to the slide 888 adjustably clamped in the guideway. In the first described embodiment of the awl actuating and feeding mechanism, the actuating cam lever and feed lever have a link connection through two dovetail slides, one of which corresponds to the slide 888 and the other of which is similar to it, clamped within the feed lever. In the present form of the awl mechanism, only one dovetail slide 888 is employed which is directly pivoted to the slide bar 884 fitting loosely within the feed lever, the loose fitting slide bar taking the place of the calibrated guide and link connection with the feed lever. One advantage of this construction is that a single adjustment only is necessary to change the feeding movement imparted to the awl whereas, with the first illustrated form of awl mechanism, two matched adjustments are required in the positions of the two dovetail slides.

As a means for adjusting conveniently the path of the awl to bring it accurately into alignment with the needle path so that the needle will enter with certainty into the perforation formed

by the awl, in the modified form of awl actuating and feeding mechanism of Fig. 73, the pivot for connecting the radius arm linkage member 24 with the feed lever 882 is constructed in the form of an eccentric sleeve 914 having a concentric portion received within a seat in the feed lever and an eccentric portion engaging an opening in the radius arm member 24 (see Fig. 75). To enable the eccentric sleeve to be clamped in any desired angular position, a collar portion of the sleeve is notched to form a series of teeth, the recesses of which fit the shape of a V-shaped projection 916 on the feed lever 882. When the desired angular position of the sleeve is reached, the sleeve is clamped in fixed relationship with the projection between a pair of teeth by a bolt 918 passing through the sleeve and into threaded engagement with a lug on the feed lever 882. Other parts of the modified form of the awl actuating and feeding mechanism are the same as in the embodiment first described and are given the same reference numerals.

Having thus described by invention, what I claim as new and desire to secure by Letters Patent of the United States is:

1. A shoe sewing machine having in combination with other stitch forming devices, a curved work penetrating instrument and a mounting for the work penetrating instrument to guide it along a path concentric to its center of curvature to form a perforation in the work and to enable movement within its plane of curvature to feed the work.
2. A shoe sewing machine having in combination with other stitch forming devices, a needle and a curved awl acting along a path concentric to its center of curvature to form a needle receiving perforation in the work and along a path within its plane of curvature into line with the needle to feed the work.
3. A shoe sewing machine having a needle and a curved awl in combination with mechanism for actuating the awl to penetrate the work along a path concentric to the awl curvature, the outer side of which path faces the needle, and mechanism for actuating the awl within its plane of curvature into line with the needle to feed the work.
4. A shoe sewing machine having a needle and a curved awl in combination with mechanism for actuating the awl to penetrate the work along a path concentric to the awl curvature, the outer side of which path faces the needle, and mechanism acting after the awl has completed its work penetrating stroke for moving the awl within its plane of curvature into line with the needle to feed the work.
5. A shoe sewing machine of the McKay type having a straight hook needle operating from one side of the work and a rotatable work supporting horn at the other side of the work, in combination with a curved awl operating from the side of the work with the needle, the outer side of the awl facing the needle, mechanism for actuating the awl along a path concentric to its curvature, towards and from the work supporting surface of the horn to form a perforation in the work on the horn, and mechanism for actuating the awl within its plane of curvature into line with the needle to feed the work along the work supporting surface of the horn.
6. A shoe sewing machine having a work support, a presser foot actuatable towards and from the work support to clamp and release the work, and a needle, in combination with a curved awl

at the side of the work with the needle, the outer side of the awl facing the needle, mechanism for actuating the awl to penetrate the work along a path concentric to its curvature while the work is clamped, and mechanism acting after the awl has completed its work penetrating stroke and the work has been released to move the awl within its plane of curvature into line with the needle while moving away from the work supporting surface of the work support to feed the work.

7. A shoe sewing machine having a work support, a presser foot actuatable towards and from the work support to clamp and release the work, and a needle, in combination with a curved awl at the side of the work with the needle, the outer side of the awl facing the needle, mechanism for actuating the awl along a path concentric to its curvature to penetrate the work while clamped and to withdraw from the work, and mechanism for actuating the awl within its plane of curvature into line with the needle during the withdrawing stroke after the work penetrating stroke is completed to feed the work and to move out of line with the needle to its original position.

8. A shoe sewing machine having a work support, a presser foot actuatable towards and from the work support to clamp the work, a needle and a curved awl, in combination with a carrier for the awl, a linkage member on which the awl carrier is pivoted to swing towards and from the needle, a radius arm for guiding the awl carrier to cause the awl to move towards and from the work along a path concentric to the awl curvature, and mechanism including a feed lever to which the radius arm is connected for moving the awl into and out of line with the needle.

9. A shoe sewing machine having a work support, a presser foot actuatable towards and from the work support to clamp the work, a needle and a curved awl, in combination with a carrier for the awl, a linkage member on which the awl carrier is pivoted to swing towards and from the needle, a radius arm for guiding the awl carrier to cause the awl to move towards and from the work along a path concentric to the awl curvature, mechanism including a feed lever to which the radius arm is connected for moving the awl into and out of line with the needle, and an adjustable connection between the feed lever and the awl carrier to bring the awl path into line with the needle.

10. A shoe sewing machine having a work support, a presser foot actuatable towards and from the work support to clamp the work, a needle and a curved awl, in combination with a carrier for the awl, a linkage member on which the awl carrier is pivoted to swing towards and from the needle, a radius arm for guiding the awl carrier to cause the awl to move towards and from the work along a path concentric to the awl curvature, mechanism including a feed lever to which the radius arm is connected for moving the awl into and out of line with the needle, and a compensating link to prevent the awl from becoming disengaged from the work while feeding the work.

11. A shoe sewing machine having a work support, a presser foot actuatable towards and from the work support to clamp the work, a straight reciprocating needle, a curved awl at the side of the work with the needle, and a carrier for the awl in combination with a linkage member on which the awl carrier is pivoted at one side of the path of the needle to cause the awl to swing towards and from the needle, a radius arm for

guiding the awl carrier in moving towards and from the work along a path concentric to the curvature of the awl when the linkage member is moved, a feed lever to which the radius arm is connected, and a compensating link connected between the feed lever and the linkage member for preventing the point of the awl from becoming disengaged from the work while feeding the work.

12. A shoe sewing machine having a main sewing shaft, a work support, a presser foot actuatable towards and from the work support to clamp the work, a needle, a curved awl and mechanism for actuating the awl along a path concentric to its curvature to cause the awl to penetrate the work, in combination with mechanism for moving the awl along a path within its plane of curvature to feed the work towards the needle including connections arranged to adjust the length of feeding movement imparted to the awl without changing substantially the depth to which the awl penetrates the work.

13. A shoe sewing machine having a main sewing shaft, a work support, a presser foot actuatable towards and from the work support to clamp the work, a needle, a curved awl and mechanism for actuating the awl along a path concentric to its curvature to cause the awl to penetrate the work, in combination with mechanism for moving the awl along a path within its plane of curvature to feed the work towards the needle including a lever operated from the sewing shaft, and a slide on the lever for changing the effective length of the lever to vary the length of feeding movement imparted to the awl without changing substantially the depth to which the awl penetrates the work.

14. A shoe sewing machine having a sewing shaft, a work support, a presser foot actuatable towards and from the work support to clamp the work, a needle, a curved awl at the side of the work with the needle, and mechanism including a crank on the sewing shaft for actuating the awl along a path concentric to its curvature to cause the awl to penetrate the work, in combination with mechanism including a cam on the sewing shaft for moving the awl along a path within its plane of curvature to feed the work.

15. A shoe sewing machine having a work support, a presser foot for clamping the work on the work engaging surface of the work support and a curved work penetrating instrument acting to form a perforation in the work substantially at right angles to the surface of the work support, in combination with mechanism for actuating said instrument along a path concentric to its curvature comprising a carrier to which said instrument is secured, an actuating lever to which the carrier is pivoted and a radius arm for guiding said carrier to cause the penetrating instrument to move towards or from the work when the actuating lever is moved.

16. A shoe sewing machine having a work support, a presser foot for clamping the work on the work engaging surface of the work support, and a curved work penetrating and feeding instrument acting to form a perforation in the work substantially at right angles to the surface of the work support, in combination with mechanism for actuating said instrument along a path concentric to its curvature comprising a carrier, an actuating lever to which the carrier is pivoted, a radius arm for guiding the carrier to cause said instrument to move towards or from the work when the actuating lever is moved, and

45

mechanism connected with the radius arm for moving said instrument within its plane of curvature to feed the work.

17. A shoe sewing machine having, in combination, a straight needle, a curved awl acting from the side of the work with the needle along a path concentric to its center of curvature to form a needle receiving perforation in the work, and a relatively straight edged projection on the awl along its outer convex surface to enable the needle to enter the awl perforation without being deflected.

18. A shoe sewing machine having, in combination, a straight needle, a curved awl acting from the side of the work with the needle along a path concentric to its center of curvature to form a needle receiving perforation in the work, a relatively straight edged projection on the awl along its outer convex surface to enable the needle to enter the awl perforation without being deflected, and mechanism for actuating the awl while engaging the work along a path within its plane of curvature from a position out of line with the needle towards a position with the portions of the perforation formed by the straight edged projection in line with the needle path.

19. A shoe sewing machine having a main sewing shaft, a work support, a presser foot actuatable towards and from the work support to clamp the work, a needle, and a curved awl at the side of the work with the needle, in combination with mechanism for actuating the awl along a path concentric to its curvature to cause the awl to penetrate the work including an awl carrier, an awl actuating lever to which the carrier is pivoted, a toggle connected to the awl actuating lever and arranged with links to be moved into positions of alignment during at least a portion of each sewing cycle, a crank on the sewing shaft for moving the central joint of the toggle, and a radius arm for guiding the awl carrier to cause the awl to move towards and from the work when the actuating lever is moved.

20. A shoe sewing machine having a main sewing shaft, a work support, a presser foot actuatable towards and from the work support to clamp the work, a needle, and a curved awl at the side of the work with the needle, in combination with mechanism for actuating the awl along a path concentric to its curvature to cause the awl to penetrate the work including an awl carrier, an awl actuating lever to which the carrier is pivoted, a toggle connected to the awl actuating lever and arranged with links to be moved into positions of alignment during at least a portion of each sewing cycle, a crank on the sewing shaft for moving the central joint of the toggle, and a radius arm for guiding the awl carrier to cause the awl to move towards and from the work when the actuating lever is moved, and mechanism for moving the awl along a path within its plane of curvature to feed the work including a cam on the sewing shaft, a follower actuated by the cam, a feed lever connected to the follower and to the awl carrier radius arm, and a compensating link connected between one end of the crank actuated toggle and the feed lever.

21. A shoe sewing machine having a main sewing shaft, a work support, a presser foot actuatable towards and from the work support to clamp the work, a needle, and a curved awl at the side of the work with the needle, in combination with mechanism for actuating the awl along a path concentric to its curvature to cause the awl to penetrate the work including an awl carrier, an

46

awl actuating lever to which the carrier is pivoted, a toggle connected to the awl actuating lever and arranged with links to be moved into positions of alignment during at least a portion of each sewing cycle, a crank on the sewing shaft for moving the central joint of the toggle, and a radius arm for guiding the awl carrier to cause the awl to move towards and from the work when the actuating lever is moved, and mechanism for moving the awl along a path within its plane of curvature to feed the work including a cam on the sewing shaft, a follower actuated by the cam, a feed lever connected to the follower and to the awl carrier radius arm, a compensating link connected between one end of the crank actuated toggle and the feed lever, and connections for changing the relative movements of the cam and feed levers to vary the feeding movement imparted to the awl.

20. 22. A shoe sewing machine having a work support, a presser foot for clamping the work on the work engaging surface of the work support, a curved work penetrating instrument acting to form a perforation in the work substantially at right angles to said surface of the work support in combination with mechanism for actuating and guiding said instrument along a path concentric to its arc of curvature comprising a four-bar linkage including the frame of the machine, a carrier to which said instrument is secured, and two members of different lengths connected by spaced pivots on said carrier the shorter member being more remote from the penetrating instrument than the longer one.

25. 23. A shoe sewing machine having a work support, a presser foot for clamping the work on the work engaging surface of the work support, a curved work penetrating instrument acting to form a perforation in the work substantially at right angles to said surface of the work support in combination with mechanism for actuating and guiding said instrument along a path concentric to its arc of curvature comprising a four-bar linkage including the frame of the machine, a carrier to which said instrument is secured, and two members of different lengths connected by spaced pivots on said carrier the shorter member being more remote from the penetrating instrument than the longer one and arranged to be moved from a position of substantially parallel relation with the longer member while the penetrating instrument is out of engagement with the work towards a position at right angles with the longer member when said instrument is in work penetrating position.

24. A shoe sewing machine having a work support, a presser foot for clamping the work on the work engaging surface of the work support, a curved work penetrating instrument acting to form a perforation in the work substantially at right angles to said surface of the work support in combination with mechanism for actuating and guiding said instrument along a path concentric to its arc of curvature comprising a four-bar linkage including the frame of the machine, a carrier to which said instrument is secured, two members of different lengths connected by spaced pivots on said carrier the shorter member being more remote from the penetrating instrument than the longer one and arranged to oscillate about a center on the frame spaced from the center of the longer member a suitable distance so far as the length of said shorter member is related to the lengths of the other linkage members to enable complete 360° rotation of the

shorter member, the point of the penetrating instrument when the shorter member is completely rotated describing a circuitous non-symmetrical path, one portion of which has a curvature approximating the arc of a circle, and mechanism for actuating the shorter member of the linkage only within the confines of said circular arc portion of the path.

25. A shoe sewing machine having a work support, a presser foot for clamping the work on the work engaging surface of the work support, a curved work penetrating instrument acting to form a perforation in the work substantially at right angles to said surface of the work support in combination with mechanisms for causing the point of said instrument to describe a closed wedge-shaped path within the plane of curvature of said instrument, two side portions of which path are substantially parallel to said instrument and comprise work penetrating and withdrawing strokes and the end portions of which path comprise work feeding and back feeding strokes, the feeding stroke being substantially separate from the parallel penetrating and withdrawing strokes and the back feeding stroke being merged with the withdrawing stroke beginning at a distance from the work support greater than the thickness of the heaviest work to be operated upon.

26. A lockstitch shoe sewing machine having a needle, a work feeding awl, a loop taker containing a supply of locking thread, and mechanisms for actuating the awl towards and from the work and in the line of the seam to feed the work, in combination with means driven by the mechanism for actuating the awl in the line of feed to pull off a length of locking thread from the supply during formation of each stitch.

27. A lockstitch shoe sewing machine having a needle, a work feeding awl, a loop taker containing a supply of locking thread, mechanism for actuating the awl towards and from the work to cause the awl to penetrate the work, and mechanism including adjustable connections for actuating the awl in the line of the seam to feed the work, in combination with means driven by the adjustable connections of said work feeding mechanism to pull off a length of locking thread from the supply during formation of each stitch, varying automatically in proportion to the change required by the adjustment in the length of feeding movement imparted to the awl.

28. A lockstitch sewing machine having stitch forming devices including a hook needle, a needle thread loop taker, a locking thread supply case about which the loop taker passes each loop of needle thread, means for pulling the needle loop from the thread case into the work to set each stitch, means for feeding the work and a locking thread measuring device, in combination with separate trains of connections for actuating the measuring device, one of which trains actuates the measuring device for each stitch to provide a length of thread substantially equal in amount to that required in drawing the stitch to a fixed depth in the work and another of which actuates the measuring device to provide a length substantially equal to the distance between successive stitches.

29. A lockstitch sewing machine having stitch forming devices including a hook needle, a needle thread loop taker, a locking thread supply case about which the loop taker passes each loop of needle thread, means for pulling the needle loop from the thread case into the work to set each

stitch, means for feeding the work and a locking thread measuring device, in combination with separate trains of connections for actuating the measuring device, one of which trains actuates the measuring device for each stitch while the stitch is being set to provide a length of thread substantially equal in amount to that required in drawing the stitch to a fixed depth in the work and another of which actuates the measuring device during feeding movement of the work to provide a length substantially equal to the distance between successive stitches.

30. A lockstitch sewing machine having stitch forming devices including a hook needle, a needle thread loop taker, a locking thread supply case about which the loop taker passes each loop of needle thread, means for pulling the needle loop from the thread case into the work to set each stitch, a work support, a presser foot for clamping the work acting on the surface of the work first engaged by the needle a sufficient distance from the needle to prevent contact therewith, means for feeding the work, and a locking thread measuring device, in combination with separate trains of mechanism for actuating the measuring device for each stitch, one of which actuates the measuring device to provide a length of thread equal in amount to that required in drawing the stitch to a fixed depth in the work plus the distance of spacing between the presser foot and the needle and another of which actuates the thread measuring device to provide a length equal to the distance between successive stitches less the distance by which the presser foot is spaced from the needle.

31. A shoe sewing machine of the McKay type having a rotatable work supporting horn, a sewing shaft, a needle, an awl at the side of the work with the needle, mechanisms driven from the sewing shaft for actuating the awl to feed the work including connections adjustable to change the length of stitch and a locking thread pull-off, in combination with pull-off actuating mechanism driven in part directly by the sewing shaft to cause a fixed length of locking thread to be withdrawn from the supply for each stitch and in part by the adjustable work feeding connections to cause the length of thread pulled off to vary as the length of stitch is adjusted.

32. A shoe sewing machine having a sewing shaft, a needle, and an awl in combination with mechanism including a crank on the sewing shaft for actuating the awl to penetrate the work, adjustable mechanism including a cam on the sewing shaft for moving the awl to feed the work, and a thread pull-off actuated in part by the crank mechanism and in part by the cam mechanism.

33. A lockstitch shoe sewing machine having a hook needle, a locking thread case, a loop taker for passing a loop of needle thread over the thread case, a locking thread measuring device, means for setting each stitch in combination with mechanism for actuating the measuring device to withdraw a length of locking thread from the thread case after the needle loop has passed over the thread case and before each stitch formed by the loop is set.

34. A shoe sewing machine having stitch forming and setting devices, a work support, a presser foot, mechanism for actuating the presser foot relatively to the work support to clamp and release the work during each sewing cycle, including an actuating lever for lifting the presser foot from the work, connections between the

actuating lever and the presser foot, and a lock for rendering the connections effective or ineffective in causing the presser foot to be lifted when the actuating lever moves, and means for urging the presser foot yieldingly toward the work support while the lock is unlocked, in combination with mechanism for holding the lock unlocked while each stitch is being set.

35. A shoe sewing machine having stitch forming and setting devices, mechanism for actuating the stitch forming and setting devices to form and set each stitch during a single sewing cycle, a work support, a presser foot, mechanism for actuating the presser foot relatively to the work support to clamp and release the work, including an actuating lever for lifting the presser foot from the work, connections between the actuating lever and the presser foot, and a lock for rendering the connections effective or ineffective in causing the presser foot to be lifted when the actuating lever is moved, and means for urging the presser foot yieldingly toward the work support while the lock is unlocked, in combination with mechanism for unlocking the lock between the times each stitch is formed and set in the work.

36. A shoe sewing machine having stitch forming and setting devices including a hook needle, a loop taker, a thread case about which the loop taker passes each loop of needle thread, and a take-up, mechanism for actuating the stitch forming and setting devices to pull each needle loop from the thread case and to set each stitch in the work during a single sewing cycle, a work support, a presser foot, mechanism for actuating the presser foot relatively to the work support to clamp and release the work, including an actuating lever for lifting the presser foot from the work, connections between the actuating lever and the presser foot, and a lock for rendering the connections effective or ineffective in causing the presser foot to be lifted when the actuating lever is moved, and means for urging the presser foot yieldingly toward the work support while the lock is unlocked, in combination with mechanism for unlocking the lock between the times each needle loop passes over the thread case and the take-up sets the stitch.

37. A shoe sewing machine having stitch forming and setting devices, mechanism for actuating the stitch forming and setting devices to form and set each stitch during a single sewing cycle, a work support, a presser foot, mechanism for actuating the presser foot relatively to the work support to clamp and release the work, including an actuating lever arranged when moved in one direction to lift the presser foot from the work, connections between the actuating lever and the presser foot, and a lock for rendering the connections effective or ineffective in lifting the presser foot when the actuating lever moves, and means for urging the presser foot yieldingly toward the work support while the lock is unlocked and the actuating lever moved to lifting position, in combination with mechanism for unlocking the lock twice during each sewing cycle, once before a stitch is formed and once after the stitch is set in the work.

38. A shoe sewing machine having stitch forming and setting devices, mechanism for actuating the stitch forming and setting devices to form and set each stitch during a single sewing cycle, a work support, a presser foot, mechanism for actuating the presser foot relatively to the work support to clamp and release the work, including

an actuating lever arranged when moved in one direction to lift the presser foot from the work, connections between the actuating lever and the presser foot, and a lock for rendering the connections effective or ineffective in lifting the presser foot when the actuating lever moves, and means for urging the presser foot yieldingly toward the work support while the lock is unlocked and the actuating lever moved to lifting position, in combination with mechanism for unlocking the lock twice during each sewing cycle, once before a stitch is formed and once after the stitch is set in the work, said actuating lever being returned to its original position from lifting position while the stitch is being set.

39. A sewing machine having stitch forming devices, a work support, a presser foot, mechanism for actuating the presser foot relatively to the work support to clamp and release the work, including a floating lever, an actuating lever connected to one point on the floating lever for lifting the presser foot from the work, a connection between another point on the floating lever and the presser foot, and a presser foot lock acting at a third point on the floating lever, and means for urging the presser foot yieldingly toward the work support while the lock is unlocked, in combination with mechanism for unlocking the presser foot lock after the actuating lever has lifted the presser foot to cause the presser foot to engage the work yieldingly and thereafter again to unlock the lock while the actuating lever returns to its original position.

40. A shoe sewing machine having stitch forming devices, a work support, a presser foot, and mechanism for actuating the presser foot relatively to the work support to clamp and release the work, in combination with means for locking the presser foot in contact with the work, comprising a vertical member connected to the presser foot, a second vertical member disposed in side by side relation with the first vertical member, a number of rolls arranged in a series vertically alongside the first vertical member, and pressure means acting intermittently during each sewing cycle at the lower end of the series of rolls to cause the rolls to press the first vertical member against the second vertical member and to enable the rolls to be lowered by gravity substantially without a frictional component when the pressure is released.

41. A sewing machine having stitch forming devices including a needle, a work support, a presser foot, a hollow presser foot carrying bar arranged to reciprocate in moving the presser foot toward and from the work, and a knife on the presser foot for severing the sewing thread at the end of a seam while the work remains in position between the work support and presser foot, in combination with mechanism for actuating the knife, comprising a reciprocable rod within the presser foot bar, and connections between the rod and knife for actuating the knife.

42. A sewing machine having stitch forming devices including a needle, a work support, a presser foot, a hollow presser foot carrying bar arranged to reciprocate in moving the presser foot toward and from the work, and a knife on the presser foot for severing the sewing thread at the end of a seam while the work remains in position between the work support and presser foot, in combination with mechanism for actuating the knife, comprising a rod within the presser foot bar, and a link arranged at an angle to the presser foot bar for actuating the knife.

43. A sewing machine having stitch forming devices including a needle, a work support, a presser foot acting to clamp the work against the work support, and a knife on the presser foot for severing the sewing thread at the end of a seam, in combination with mechanism for actuating the thread severing knife, comprising a shaft rotatably mounted on the presser foot, a slide on which the knife is supported connected to the shaft and a guideway for the slide in the presser foot disposed at an angle to the surface of the work engaged by the presser foot.

44. A sewing machine having stitch forming devices including a needle, a work support, a presser foot acting to clamp the work against the work support, and a knife on the presser foot for severing the sewing thread at the end of a seam, in combination with mechanism for actuating the thread severing knife, comprising an actuating rod having rack teeth, a pinion rotatably mounted in the presser foot meshing with the rack teeth on the actuating rod, a knife supporting slide and a guideway in the presser foot disposed at an angle to the actuating rod having rack teeth also meshing with the pinion.

45. A sewing machine having stitch forming devices including a needle, a work support, and a presser foot, in combination with means for severing the sewing thread while the work remains in position between the work support and presser foot, comprising a hollow tubular knife the cutting edge of which is formed with a face across the knife at an acute angle to its length.

46. A sewing machine having stitch forming devices including a needle, a work support, a presser foot, a hollow presser foot carrying bar arranged to reciprocate in moving the presser foot toward and from the work support, and a knife on the presser foot for severing the sewing thread while the work remains in position between the work support and presser foot, in combination with mechanism for actuating the thread severing knife, comprising a rod slidably mounted in the presser foot bar, a bell crank on the presser foot bar having one arm connected to the rod, and a link extending at right angles to the presser foot bar connected to the other arm of the bell crank.

47. A lockstitch shoe sewing machine having a hook needle, a needle thread loop taker, a locking thread supply case about which the loop taker passes each loop of needle thread, and means for pulling the needle loop from the thread case and into the work to set each stitch, in combination with a locking thread measuring device comprising thread gripping jaws acting along the lead of locking thread passing from the thread case to withdraw locking thread from the supply after each needle loop is pulled from the loop taker and to remain in gripping engagement with the thread while the stitch including said needle loop is being set.

48. A lockstitch shoe sewing machine having a hook needle, a needle thread loop taker, a locking thread supply case about which the loop taker passes each loop of needle thread, and means for pulling the needle loop from the thread case and into the work to set each stitch, in combination with a locking thread measuring device comprising thread gripping jaws, mechanism for reciprocating the jaws along the lead of thread extending from the thread case timed to withdraw thread from the supply after each needle loop is pulled from the thread case, and mechanism for closing the jaws against the thread and

for holding the jaws closed while the stitch, including the needle loop, is being set.

49. A lockstitch shoe sewing machine having a hook needle, a needle thread loop taker, a locking thread supply case about which the loop taker passes each loop of needle thread, and means for pulling the needle loop from the thread case and into the work to set each stitch, in combination with a locking thread measuring device comprising thread gripping jaws, mechanism for reciprocating the jaws along the lead of thread extending from the thread case timed to withdraw thread from the supply after each needle loop is pulled from the thread case and until the locking thread is brought into engagement with the upper surface of the work and for holding the jaws closed on the locking thread until the stitch setting pull on the needle loop is relieved.

50. A lockstitch shoe sewing machine having a hook needle, a needle thread loop taker, a locking thread supply case about which the loop taker passes each loop of needle thread, and means for pulling the needle loop from the thread case and into the work to set each stitch in combination with a locking thread measuring device comprising thread gripping jaws acting in each sewing cycle along the locking thread passing from the supply in the thread case to grip and measure said thread after a needle loop is pulled from the thread case and to release the grip on the locking thread after the stitch including said needle loop is set.

51. A lockstitch shoe sewing machine having a hook needle, a needle thread loop taker, a locking thread supply case about which the loop taker passes each loop of needle thread, and means for pulling the needle loop from the thread case and into the work to set each stitch, in combination with a locking thread measuring device comprising thread gripping jaws, mechanism for actuating the jaws in one direction to withdraw locking thread from the supply and in the opposite direction after each stitch is set to return the jaws to starting position, and mechanism for closing the jaws on the thread while the jaws are being actuated to withdraw thread, for holding the jaws closed on the locking thread while the stitch including said needle loop is being set and for opening the jaws after the stitch is set and before a new needle loop is engaged by the loop taker to enable the new needle loop to pass freely over the thread case.

52. A lockstitch shoe sewing machine having a hook needle, a needle thread loop taker, a locking thread supply case about which the loop taker passes each loop of needle thread, means for pulling the needle loop from the thread case and into the work to set each stitch, work feeding means and a locking thread measuring device for withdrawing thread from the supply in the thread case, in combination with adjustable mechanism for actuating the measuring device to regulate the depth to which the stitches are to be set in the work, and other adjustable mechanism for actuating the work feeding means connected to the measuring device to provide sufficient locking thread between stitches without changing the depth to which the stitches are set in the work as the feeding means actuating mechanism is adjusted.

53. A lockstitch shoe sewing machine having a hook needle, a needle thread loop taker, a locking thread supply case about which the loop taker passes each loop of needle thread, means for

pulling the needle loop from the thread case and into the work to set each stitch, work feeding means and a locking thread measuring device for withdrawing thread from the supply in the thread case, in combination with mechanism for actuating the measuring device, connections in said actuating mechanism adjustable to regulate the depth to which the stitches are to be set in the work without changing the adjustment of work feed, and other adjustable connections in said mechanism to cause a change in work feeding adjustment of the work feeding means and an equal change in the adjustment of the locking thread withdrawn from the supply.

54. A lockstitch shoe sewing machine having a hook needle, a loop taker, means containing a supply of locking thread about which the loop taker passes each loop of thread carried through the work by the needle, a locking thread measuring and other devices, and a sewing shaft for actuating said devices, in combination with mechanisms between the sewing shaft and the measuring device to cause the measuring device to withdraw thread from the supply comprising a crank on the sewing shaft, suitable connections actuated by the crank adjustable to regulate the depth to which the stitches are set in the work, and trains of cam actuated connections, one of said trains also being adjustable to increase or decrease the amount of locking thread withdrawn from the supply.

55. A lockstitch shoe sewing machine having a hook needle, a loop taker, means containing a supply of locking thread about which the loop taker passes each loop of thread carried through the work by the needle, a locking thread measuring and other devices, and a sewing shaft for actuating said devices, in combination with mechanisms between the sewing shaft and the measuring device to cause the measuring device to withdraw thread from the supply comprising a crank on the sewing shaft, suitable connections between the crank and the measuring device to impart a thread withdrawing movement to the measuring device corresponding to the depth to which each stitch is to be set in the work, a cam on the sewing shaft and connections between the cam and the measuring device to impart movement to the measuring device corresponding to the distance between stitches.

56. A lockstitch shoe sewing machine having a hook needle, a loop taker, means containing a supply of locking thread about which the loop taker passes each loop of thread carried through the work by the needle, a locking thread measuring and other devices, and a sewing shaft for actuating said devices, in combination with mechanisms between the sewing shaft and the measuring device to cause the measuring device to withdraw thread from the supply comprising a crank on the sewing shaft, suitable connections between the crank and the measuring device to impart a shifting movement to the measuring device, a cam on the sewing shaft, and other connections for actuating the measuring device near one end of the movement imparted by the crank to the measuring device.

57. A lockstitch shoe sewing machine having a hook needle, a loop taker, means containing a supply of locking thread about which the loop taker passes each loop of thread carried through the work by the needle, a locking thread measuring and other devices, and a sewing shaft for actuating said devices, in combination with mechanisms between the sewing shaft and the measuring de-

vice to cause the measuring device to withdraw thread from the supply comprising a crank on the sewing shaft, suitable connections between the crank and the measuring device to impart a shifting movement to the measuring device, and first cam actuated connections for imparting a measuring movement to the measuring device near the beginning of its thread withdrawing stroke, and second cam actuated connections for imparting a measuring movement to the measuring device between the movements imparted by the first cam connections and the crank connections.

58. A lockstitch shoe sewing machine having a hook needle, a loop taker, means containing a supply of locking thread about which the loop taker passes each loop of thread carried through the work by the needle, a locking thread measuring and other devices, and a sewing shaft for actuating said devices, in combination with mechanisms between the sewing shaft and the measuring device to cause the measuring device to withdraw thread from the supply comprising a crank on the sewing shaft, suitable connections between the crank and the measuring device to impart a shifting movement to the measuring device, and first cam actuated connections for imparting a measuring movement to the measuring device near the beginning of its thread withdrawing stroke, second cam actuated connections for imparting a measuring movement to the measuring device between the movements imparted by the first cam connections and the crank connections, and means for adjusting the first cam connections to regulate the depth to which each stitch is set in the work.

59. A lockstitch shoe sewing machine having a hook needle, a loop taker, means containing a supply of locking thread about which the loop taker passes each loop of thread carried through the work by the needle, a locking thread measuring and other devices, and a sewing shaft for actuating said devices, in combination with mechanisms between the sewing shaft and the measuring device to cause the measuring device to withdraw thread from the supply comprising a crank on the sewing shaft, suitable connections between the crank and the measuring device to impart a shifting movement to the measuring device, and first cam actuated connections for imparting a measuring movement to the measuring device near the beginning of its thread withdrawing stroke, second cam actuated connections for imparting a measuring movement to the measuring device between the movements imparted by the first cam connections and the crank connections, work feeding means actuated by the second cam connections, means for adjusting the second cam connections to regulate the length of feed and simultaneously the amount of thread withdrawn from the supply, and means for adjusting the first cam connections to regulate the uniform depth at which each stitch is set in the work regardless of the adjustment of the second cam connections.

60. A lockstitch shoe sewing machine having a hook needle, a needle thread loop taker, a locking thread supply case about which the loop taker passes each loop of needle thread, means for pulling the needle loop from the thread case and into the work to set each stitch, and work feeding means, in combination with a locking thread measuring device acting in each sewing cycle after a needle loop is drawn from the thread case to withdraw locking thread from the sup-

ply in an amount corresponding to the depth at which each stitch is to be set in the work, to hold the locking thread while each stitch is being set and to withdraw thread in a further amount corresponding to the length of a stitch after the stitch setting tension on the thread is relieved.

61. A lockstitch shoe sewing machine having a hook needle, a needle thread loop taker, a locking thread supply case about which the loop taker passes each loop of needle thread, means for pulling the needle loop from the thread case and into the work to set each stitch, and work feeding means, in combination with a locking thread measuring device, mechanism for actuating the measuring device in each sewing cycle after a needle loop is drawn from the thread case to cause an amount of locking thread to be withdrawn from the supply in an amount corresponding to the depth at which each stitch is to be set in the work and to hold the locking thread while each stitch is being set, and connections between the feeding means and the measuring device for actuating the measuring device to withdraw locking thread in a further amount corresponding to the length of a stitch.

62. A lockstitch shoe sewing machine having a hook needle, a needle thread loop taker, a locking thread supply case about which the loop taker passes each loop of needle thread, means for pulling the needle loop from the thread case and into the work to set each stitch, and work feeding means, in combination with a locking thread measuring device, mechanism for actuating the measuring device in each sewing cycle after a needle loop is drawn from the thread case to cause an amount of locking thread to be withdrawn from the supply in an amount corresponding to the depth at which each stitch is to be set in the work and to hold the locking thread while each stitch is being set, connections between the feeding means and the measuring device for actuating the measuring device to withdraw locking thread in a further amount corresponding to the length of a stitch, and a presser foot acting on the work in close proximity to the point of needle operation to press the locking thread against the surface of the work before the succeeding needle loop is passed about the thread case.

63. A lockstitch shoe sewing machine having a hook needle, a needle thread loop taker, a locking thread supply case about which the loop taker passes each loop of needle thread, means for pulling the needle loop from the thread case and into the work to set each stitch, a locking thread measuring device comprising thread gripping jaws, and thread guides on the thread case for holding the locking thread in the path of movement of the gripping jaws, in combination with mechanism for actuating the jaws in each sewing cycle to a position between the thread guides to measure thread and out from between the guides to enable free passage of each needle loop about the thread case.

64. A lockstitch shoe sewing machine having a hook needle, a hollow rotary needle thread loop taker, a locking thread case removable from the front of the loop taker, and locking thread gripping jaws actuatable diametrically across the front of the loop taker to withdraw locking thread, in combination with mechanisms for actuating the jaws away from the front of the loop taker during each sewing cycle, to render the thread case free of obstruction.

65. A lockstitch shoe sewing machine having a hook needle, a hollow rotary needle thread loop taker, a locking thread case removable from the front of the loop taker, and locking thread gripping jaws actuatable diametrically across the front of the loop taker to withdraw locking thread, in combination with mechanism for actuating the jaws diametrically away from the front of the loop taker including quickly disconnectible connections shiftable to render the thread case free of obstruction.

66. A lockstitch shoe sewing machine having a hook needle, a hollow rotary needle thread loop taker, a locking thread case removable from the front of the loop taker, and locking thread gripping jaws actuatable diametrically across the front of the loop taker to withdraw locking thread, in combination with means for actuating the jaws including mechanism for moving the jaws away from the front of the loop taker to render the thread case free of obstruction and a link connected with one of the jaws for opening the jaws while being moved away from the loop taker.

67. A lockstitch sewing machine having a sewing shaft, stitch forming devices including a hook needle, a hollow rotary loop taker actuated by the sewing shaft, a locking thread supply case removable from the front of the loop taker, locking thread gripping jaws actuatable diametrically across the front of the loop taker to measure thread from the supply in the thread case, connections actuated by the sewing shaft for imparting a limited thread measuring movement to the gripping jaws, means for actuating the jaws beyond the limits of the thread measuring movement to render the thread case free of obstruction, and a cam on the sewing shaft for opening and closing the jaws, in combination with a link actuated by the cam and arranged substantially at right angles to the path through which the jaws move while measuring thread to cause the jaws to be opened when operated beyond the limits of thread measuring movement.

68. A lockstitch shoe sewing machine having a needle, a rotary loop taker containing a supply of locking thread, in combination with a locking thread measuring device actuatable to draw off from the supply in the loop taker a length of locking thread during each sewing cycle comprising a reciprocating tubular member having a jaw thereon and a second jaw pivoted within the tubular member to swing towards and from the first-mentioned jaw.

69. A lockstitch shoe sewing machine having a needle, a rotary loop taker containing a supply of locking thread, in combination with a locking thread measuring device actuatable to draw off from the supply in the loop taker a length of locking thread during each sewing cycle comprising a reciprocating tubular member having a jaw thereon, a second jaw pivoted within the tubular member to swing towards and from the first-mentioned jaw, and a grooved guideway for the tubular jaw member into the groove of which a portion of said second jaw projects to prevent rotation of the tubular member in the guideway.

70. A lockstitch shoe sewing machine having a hook needle, a hollow rotary loop taker, a locking thread case removable from the front of the loop taker, and locking thread gripping jaws actuatable diametrically across the front of the loop taker to withdraw locking thread for each stitch, in combination with mechanisms for actuating the jaws during each sewing cycle comprising three mechanisms, one of which moves

the jaws while gripping the thread through a fixed distance, another of which moves the jaws while gripping the thread through a variable distance depending upon the length of each stitch, and a third of which causes the jaws to be shifted to render the thread case free of obstruction.

71. A lockstitch shoe sewing machine having a hook needle, a hollow rotary loop taker, a locking thread case removable from the front of the loop taker, and locking thread gripping jaws actuatable diametrically across the front of the loop taker to withdraw locking thread for each stitch, in combination with mechanisms for actuating the jaws during each sewing cycle comprising three mechanisms, one of which moves the jaws while gripping the thread through a fixed distance, another of which moves the jaws while gripping the thread through a variable distance depending upon the length of each stitch, and a third of which causes the jaws to be shifted to render the thread case free of obstruction, and quickly disconnectible connections in one of said mechanisms for enabling the jaws to be shifted away from the thread case in any position of the stitch forming devices.

72. A lockstitch shoe sewing machine having a hook needle, a loop taker, a supply of locking thread about which the loop taker passes each loop carried through the work by the needle, a locking thread measuring and other devices, and a sewing shaft for actuating said devices, in combination with mechanisms for actuating the measuring device to cause thread to be withdrawn from the supply, comprising a cam on the sewing shaft and a pair of cam rolls engaging the same track in the cam but displaced in angular relation about the cam.

73. A lockstitch shoe sewing machine having stitch forming devices including a hook needle, a hollow rotary needle loop taker, a locking thread supply which is accessible for replenishment from the front of the loop taker, and locking thread gripping jaws actuatable diametrically across the front of the loop taker to withdraw thread, and a sewing shaft for actuating said devices in combination with mechanisms for moving the jaws toward and away from the front of the loop taker during each sewing cycle, comprising a cam and a pair of rolls engaging the same track in the cam but displaced in angular relation about the cam to be moved in sequence.

74. A sewing machine having stitch forming devices including a reciprocating hook needle, a cylindrical rotary loop taker provided with a beak and an inclined loop spreading shoulder on its outer cylindrical surface, in combination with a loop spreader for opening the needle loop in the path of the loop taker beak and for laying it progressively along the loop spreading shoulder as the loop taker rotates.

75. A sewing machine having stitch forming devices including a reciprocating hook needle, a cylindrical rotary loop taker provided with a beak and an inclined loop spreading shoulder on its outer cylindrical surface, in combination with a loop spreader for opening the needle loop in the path of the loop taker beak, and mechanism for actuating the spreader at the same rate of speed as that at which the loop spreading shoulder on the loop taker moves past the path of the spreader to lay the thread of the loop progressively along the shoulder of the loop taker.

76. A sewing machine having stitch forming

devices including a needle, a cylindrical rotary loop taker provided with an external circular series of helical gear teeth with a recess between two adjacent gear teeth extending inwardly beyond the teeth for the reception of a needle loop, and a helical driving gear engaging the teeth on the loop taker, in combination with a loop spreader reciprocating toward and from the needle in a path at an angle to the teeth across the surface of the loop taker to lay the needle thread progressively in the recess as the loop taker rotates.

77. A sewing machine having a needle and other stitch forming devices, in combination with a rotary loop taker comprising a hollow cylindrical body provided with an external series of uniformly spaced helical gear teeth and a circular guide plate having an open needle loop receiving hook at one end of the loop taker body, the throat of which hook is aligned with the recess between two teeth of the loop taker body, and a helical driving gear engaging the teeth on the body to rotate the loop taker in a direction to cause the needle loop to be engaged progressively with the side surface of a tooth bordering the recess.

78. A sewing machine having a needle and other stitch forming devices, in combination with a rotary loop taker comprising a hollow, cylindrical body provided with an external series of uniformly spaced helical gear teeth and a circular guide plate having an open needle loop receiving hook at one end of the loop taker body, the throat of which hook is aligned with the recess between two teeth of the loop taker body, a helical driving gear engaging the teeth on the body to rotate the loop taker in a direction to cause the needle loop to be engaged progressively with the side surface of a tooth bordering the recess, and a raceway for the periphery of the guide plate within which the loop taker rotates, said loop receiving hook being formed within the periphery of the circular plate.

79. A sewing machine having a needle and other stitch forming devices, in combination with a rotary loop taker comprising a hollow, cylindrical body provided with an external series of uniformly spaced helical gear teeth and a circular guide plate having an open needle loop receiving hook at one end of the loop taker body, the throat of which hook is aligned with the recess between two teeth of the loop taker body, a helical driving gear engaging the teeth on the body to rotate the loop taker in a direction to cause the needle loop to be engaged progressively with the side surface of a tooth bordering the recess, a raceway for the periphery of the guide plate within which the loop taker rotates, said loop receiving hook being formed within the periphery of the circular plate, and a backing plate at the other end of the loop taker body having a needle loop receiving hook, the throat of which is aligned with the same recess as the throat of the guide plate hook.

80. A sewing machine having a needle, a rotary loop taker comprising a hollow, cylindrical body provided with a circular series of teeth and a driving gear engaging the teeth on the loop taker body, in combination with means for insuring assembly of the loop taker and driving gear in proper timed relation, including an annular notched plate at one end of the loop taker body, and a tongue on the driving gear fitting the notch in the plate.

81. A sewing machine having stitch forming

devices including a reciprocating hook needle, a loop taker rotating a plurality of times during a single reciprocation of the needle, and a loop spreader, in combination with mechanism for actuating the loop spreader with a continuous movement through a series of lobate paths to open the loop of thread carried by the needle for the loop taker during one reciprocation of the needle.

82. A sewing machine having stitch forming devices including a reciprocating hook needle, a loop taker rotating a plurality of times during a single reciprocation of the needle, and a loop spreader, in combination with mechanism for actuating the loop spreader with a continuous movement through a number of lobate paths, at least as many as the number of rotations of the loop taker during a single reciprocation of the needle, to open the loop of thread carried by the needle for the loop taker during movement through one of said paths.

83. A sewing machine having a needle, a loop spreader and a loop taker comprising a hollow, cylindrical body and a pair of annular end plates, in combination with a locking thread case within the loop taker fitting the inner surface of the loop taker body and retained axially in position relatively to said loop taker by the end plates, and means for preventing rotation of the thread case with the loop taker.

84. A sewing machine having a needle, a loop spreader and a loop taker comprising a hollow, cylindrical body and a pair of annular end plates, in combination with a locking thread case within the loop taker fitting the inner surface of the loop taker body and retained axially in position relatively to said loop taker by the end plates, means for preventing rotation of the thread case with the loop taker, and common driving connections between the loop spreader mechanism and the loop taker.

85. A sewing machine having a needle, a rotary loop taker comprising a hollow, cylindrical body provided with a circular series of teeth and a driving gear engaging the teeth on the loop taker body, in combination with a supporting shaft for the loop taker driving gear, a driver rotatable on the supporting shaft, and a friction clutch for releasably securing the driver to the supporting shaft.

86. A sewing machine having a needle, a rotary loop taker comprising a hollow, cylindrical body provided with a circular series of teeth and a driving gear engaging the teeth on the loop taker body, in combination with a supporting shaft for the loop taker driving gear, a splined sleeve secured to the supporting shaft, a collar mounted for sliding movement and secured from relative rotation on the splined sleeve, an end face cam and groove connection between the collar and the driver, and yielding means for pressing the collar and driver together to provide a slip joint between the driver and the loop taker gear supporting shaft.

87. A sewing machine having a needle and a rotary loop taker, comprising a hollow cylindrical body provided with external gear teeth, in combination with a raceway for the loop taker formed with a fixed portion within which the loop taker is received, and a movable member pivoted to the fixed portion to enable release of the loop taker when the movable member is swung about its pivot away from the fixed portion.

88. A sewing machine having a needle and a rotary loop taker, comprising a hollow cylindri-

cal body provided with external gear teeth, in combination with a raceway for the loop taker formed with a fixed portion within which the loop taker is received, a movable member pivoted to the fixed portion to enable release of the loop taker when the movable member is swung about its pivot away from the fixed portion, and means for locking the movable raceway member to the fixed portion, comprising a face plate formed with flanges cooperating with the fixed portion and movable member to prevent separation when in engagement therewith.

89. A sewing machine having a needle and a rotary loop taker, comprising a hollow cylindrical body provided with external gear teeth, in combination with a raceway for the loop taker formed with a fixed portion within which the loop taker is received, a movable member pivoted to the fixed portion to enable release of the loop taker when the movable member is swung about its pivot away from the fixed portion, and means for locking the movable raceway member to the fixed portion, comprising a face plate formed with flanges cooperating with the fixed portion and movable member to prevent separation when in engagement therewith, said face plate providing a raceway thrust surface to prevent endwise displacement of the loop taker from the raceway.

90. A shoe sewing machine having stitch forming devices including a reciprocating straight hook needle, a looper taker rotating about an axis at a substantial angle to the needle, and a loop lifter, in combination with mechanisms for actuating the needle loop taker and lifter to cause the thread to be disengaged from the needle hook while the threaded needle is being withdrawn from the work before being engaged with the loop taker.

91. A shoe sewing machine having stitch forming devices including a reciprocating straight hook needle, a looper taker rotating about an axis at a substantial angle to the needle, and a loop lifter, in combination with mechanisms for actuating the needle and lifter to cause the thread to be disengaged from the needle hook, and means for opening the loop of thread formed by the needle for the loop taker after being disengaged from the needle hook.

92. A shoe sewing machine having stitch forming devices including a hook needle, a rotary loop taker, a loop lifter, and a loop spreader, in combination with mechanisms for actuating the needle, loop lifter and spreader to cause the thread to be disengaged from the needle hook and the spreader to open the needle loop after the loop is disengaged from the needle hook.

93. A shoe sewing machine having stitch forming devices including a hook needle, a looper, a thread finger for measuring a sufficient length of thread between the looper and the last formed stitch in the work to enable movement of the threaded needle hook through the work without substantial tension, a loop taker, and a loop lifter, in combination with mechanisms for actuating the needle and lifter to cause the thread to be disengaged from the needle hook before the length measured by the thread finger is exhausted.

94. A shoe sewing machine having, in combination, stitch forming devices including a straight hook needle, a loop lifter and a loop spreader, a rockshaft to which the lifter is secured for swinging the lifter toward and from the needle, and mechanism for actuating the rockshaft during movement of the needle away

from the work to cause the loop lifter to overtake the needle and disengage the loop before the loop is engaged by the loop spreader.

95. A shoe sewing machine having, in combination, stitch forming devices including a straight hook needle and a loop lifter, a rock-shaft, a clamp at the end of the shaft for receiving the loop lifter, mechanism for actuating the shaft to cause the lifter to disengage the loop from the needle, and an eccentric bushing in the clamp for adjusting the position of the loop lifter relatively to the needle while disengaging the loop.

96. A shoe sewing machine having stitch forming devices including a reciprocating hook needle, a loop taker, and a loop spreader, in combination with mechanism for actuating the loop spreader with a continuous movement through a series of lobate paths during one reciprocation of the needle.

97. A shoe sewing machine having stitch forming devices including a reciprocating hook needle, a loop taker, and a loop spreader, in combination with mechanism for actuating the loop spreader with a continuous movement through a series of lobate paths during one reciprocation of the needle, one of which paths intersects the loop of thread carried through the work by the needle.

98. A shoe sewing machine having stitch forming devices including a reciprocating hook needle, a loop taker, and a loop spreader, in combination with a crank for actuating the loop spreader through a lobate path during each rotation of the crank, and a planetary gear to which the crank is connected for changing the shape of the loop spreader path periodically to cause it to intersect the loop of thread carried through the work by the needle during one only of a continuous series of such paths.

99. A shoe sewing machine having stitch forming devices including a reciprocating hook needle, a loop taker, and a loop spreader, in combination with a continuously driven member, a planet gear carried by said member, and a crank on the planet gear for actuating the loop spreader through a series of incongruent lobate paths during one reciprocation of the needle, one of which paths intersects the loop of thread carried by the needle.

100. A shoe sewing machine having stitch forming devices including a reciprocating hook needle, a loop taker, and a loop spreader, in combination with a continuously driven sleeve member, a shaft mounted within the sleeve member, a spur gear on the shaft, a planet gear on the sleeve member meshing with the spur gear, and a crank on the planet gear for actuating the loop spreader through a series of incongruent lobate paths during one reciprocation of the needle, one of which paths intersects the loop of thread carried through the work by the needle.

101. A McKay type shoe sewing machine having stitch forming devices including a straight hook needle, a rotatable shoe supporting horn arranged to extend within the shoe, needle threading mechanism mounted in the horn to turn with the horn, and a sewing shaft for reciprocating the needle into and out of operative relation with the needle threading mechanism, in combination with mechanism for turning the needle about its longitudinal axis to rotate the needle hook with the horn as the horn is turned substantially less in degree than the rotation of the horn.

102. A McKay type shoe sewing machine hav-

ing stitch forming devices including a straight hook needle, a rotatable shoe supporting horn arranged to extend within the shoe, needle threading mechanism mounted in the horn to turn with the horn, and a sewing shaft for reciprocating the needle into and out of operative relation with the needle threading mechanism, in combination with mechanism for turning the needle about its longitudinal axis to rotate the needle hook with the horn as the horn is turned substantially less in degree than the rotation of the horn and proportionately with the horn rotation throughout the rotary movement of the horn.

103. A McKay type shoe sewing machine having stitch forming devices including a straight hook needle, a rotatable shoe supporting horn arranged to extend within the shoe, a sewing shaft for reciprocating the needle toward and from the horn, in combination with mechanism for turning the needle about its longitudinal axis to rotate the needle hook with the horn as the horn is turned substantially less in degree than the rotation of the horn, needle threading mechanism mounted in the horn to turn with the horn and constructed and arranged to lay the thread in the hook of the needle while the angular position of the needle hook is substantially different from that of the horn, said needle turning mechanism acting proportionately with the horn rotation with the maximum difference in degree of needle rotation as compared with horn rotation within the range of effective operation of the needle threading mechanism.

104. A McKay type shoe sewing machine having stitch forming devices including a straight hook needle, a reciprocable needle bar, a rotatable shoe supporting horn arranged to extend within and turn with the shoe as the shoe is presented to the stitch forming devices, and a sewing shaft for reciprocating the needle bar, in combination with the mechanism for turning the needle about its longitudinal axis to rotate the needle hook with the horn, comprising a rotatable member having a splined connection with the needle bar to enable the needle bar to reciprocate while the rotatable member remains stationary, and means for turning the rotatable member.

105. A McKay type shoe sewing machine having stitch forming devices including a straight hook needle, a reciprocable needle bar, a rotatable shoe supporting horn arranged to extend within and turn with the shoe as the shoe is presented to the stitch forming devices, and a sewing shaft for reciprocating the needle bar, in combination with mechanism for turning the needle about its longitudinal axis to rotate the needle hook with the horn, comprising, a gear member having a splined connection with the needle bar to enable the needle bar to reciprocate while the gear member remains stationary, a gear segment meshing with the gear member, and connections between the horn and the segment for rotating the gear member as the horn is turned.

106. A McKay type shoe sewing machine having stitch forming devices including a straight hook needle, a reciprocable needle bar, a rotatable shoe supporting horn arranged to extend within and turn with the shoe as the shoe is presented to the stitch forming devices, and a sewing shaft for reciprocating the needle bar, in combination with mechanism for turning the needle about its longitudinal axis to rotate the

needle hook with the horn, comprising rotatable members for connecting the needle bar and the horn to turn the needle hook as the horn is rotated, a ratchet wheel on one of the rotatable members, and pawls actuated intermittently toward and from the ratchet wheel to lock and unlock the needle rotating connections during sewing operations.

107. A McKay type shoe machine having stitch forming devices including a straight hook needle, a reciprocable needle bar, a rotatable shoe supporting horn arranged to extend within and turn with the shoe as the shoe is presented to the stitch forming devices, and a sewing shaft for reciprocating the needle bar, driving and stopping mechanism for the sewing shaft acting to bring the machine to rest with the stitch forming devices in predetermined stopping positions, and mechanism for turning the needle about its longitudinal axis, in combination with a device actuated by the driving and stopping mechanism for securing the needle bar when the machine is brought to rest.

108. A shoe sewing machine having a compartmented frame, stitch forming devices including a straight needle and an awl, a vertical needle bar mounted at the front of the frame, and a horizontal continuously rotating sewing shaft disposed with one end adjacent to the needle bar, in combination with mechanisms for actuating the needle and awl from the sewing shaft located in separate compartments of the frame along the sewing shaft.

109. A shoe sewing machine having a compartmented frame, stitch forming devices including a straight needle and an awl, a vertical needle bar mounted at the front of the frame, and a horizontal continuously rotating sewing shaft disposed with one end adjacent to the needle bar, in combination with mechanisms for actuating the needle and awl from the sewing shaft located in separate compartments of the frame along the sewing shaft, and rockshafts extending parallel to the sewing shaft for transferring the motions produced by said mechanisms to the respective stitch forming devices.

110. A shoe sewing machine having a compartmented frame, stitch forming devices including a straight needle and an awl, a vertical needle bar mounted at the front of the frame, and a horizontal continuously rotating sewing shaft disposed with one end adjacent to the needle bar, in combination with mechanisms for actuating the needle and awl toward and from the work and for turning the needle located each in one of three separate compartments of the frame along the sewing shaft.

111. A shoe sewing machine having a compartmented frame, stitch forming devices including a straight needle and an awl, a vertical needle bar mounted at the front of the frame, and a horizontal continuously rotating sewing shaft disposed with one end adjacent to the needle bar, in combination with mechanisms for actuating the needle and awl toward and from the work located in separate compartments of the frame along the sewing shaft, and mechanism outside the frame at the front of the machine for imparting a feeding movement to the awl.

112. A shoe sewing machine having a compartmented frame, stitch forming devices including a straight needle, an awl, and means for supplying locking thread, a vertical needle bar mounted at the front of the machine, and a horizontal continuously rotating sewing shaft disposed with one end adjacent to the needle bar, in

combination with interconnected mechanisms outside the frame at the front of the machine for imparting a feeding movement to the awl and for pulling off locking thread from the supply means.

113. A shoe sewing machine having a compartmented frame, stitch forming devices including a straight needle and an awl, a vertical needle bar mounted at the front of the frame, and a horizontal continuously rotating sewing shaft disposed with one end adjacent to the needle bar, in combination with mechanisms for actuating the needle and awl from the sewing shaft, and a driving and stopping mechanism located each in one of several separate compartments of the frame along the sewing shaft.

114. A sewing machine having stitch forming devices including a needle and a take-up for setting each stitch in the work, a sewing shaft for actuating the stitch forming devices, and driving and stopping mechanism for bringing the sewing shaft to rest with the needle disengaged from the work before the take-up reaches a stitch setting position, in combination with mechanism acting after the sewing shaft has been brought to rest to cause the final stitch in a seam to be set.

115. A sewing machine having stitch forming devices including a needle and a take-up for setting each stitch in the work, a sewing shaft for actuating the stitch forming devices, and driving and stopping mechanism for bringing the sewing shaft to rest with the needle disengaged from the work before the take-up reaches a stitch setting position, in combination with auxiliary mechanism set in operation by the driving and stopping mechanism while bringing the sewing shaft to rest for changing the relative positions between the take-up and sewing shaft after the sewing shaft is brought to rest to cause the final stitch in a seam to be set.

116. A sewing machine having stitch forming devices including a needle and a take-up for setting each stitch in the work, a sewing shaft for actuating the stitch forming devices, and a secondary shaft for actuating the take-up in combination with a set of differential gears, two members of which respectively are driven from the sewing shaft and which in turn drive the secondary shaft, and a third member of which is set in motion by the driving and stopping mechanism while bringing the sewing shaft to rest to cause the take-up to set the final stitch in the seam.

117. A sewing machine having stitch-forming devices including a hook needle, a looper and a thread finger within which the looper lays the thread before applying the thread to the needle to provide thread for one side of each needle loop, a sewing shaft for actuating the stitch-forming devices during sewing, and driving and stopping mechanism for bringing the sewing shaft to rest with the needle disengaged from the work, in combination with auxiliary mechanism acting after the sewing shaft has been brought to rest to cause the looper to lay the thread in the thread finger.

118. A sewing machine having stitch-forming devices including a hook needle, a looper and a thread finger within which the looper lays the thread before applying the thread to the needle to provide thread for one side of each needle loop, a sewing shaft for actuating the stitch-forming devices during sewing, and driving and stopping mechanism for bringing the sewing shaft to rest with the needle disengaged from the work, in combination with auxiliary mechanism set in op-

eration by the driving and stopping mechanism to actuate the looper and thread finger relatively to each other into positions where the thread is trapped between the thread finger and looper.

119. A sewing machine having stitch-forming devices including a hook needle, a looper and a thread finger within which the looper lays the thread before applying the thread to the needle to provide thread for one side of each needle loop, a sewing shaft for actuating the stitch-forming devices during sewing, driving and stopping mechanism for bringing the sewing shaft to rest with the needle disengaged from the work, and a thread cutter set in operation by the driving and stopping mechanism to sever the thread of the final stitch in a seam, in combination with mechanism acting before the thread is severed to lay the thread in the thread finger.

120. A sewing machine having stitch-forming devices including a hook needle, a looper and a thread finger within which the looper lays the thread before applying the thread to the needle to provide thread for one side of each needle loop, a sewing shaft for actuating the stitch-forming devices during sewing, driving and stopping mechanism for bringing the sewing shaft to rest with the needle disengaged from the work, and a thread cutter set in operation by the driving and stopping mechanism to sever the thread of the final stitch in a seam, in combination with mechanism acting before the thread is severed to lay the thread in the thread finger and thereafter to actuate the looper and thread finger relatively to each other into positions where the thread is trapped against displacement from the thread finger when the tension is released as a result of severing the thread.

121. A shoe sewing machine of the McKay type having stitch forming devices including a straight hook needle operating from one side of the work, a rotatable work supporting horn at the other side of the work, a take-up for setting each stitch in the work, and needle threading devices in the horn, a main sewing shaft for actuating the stitch forming devices, a secondary shaft in the horn, connections driven by the secondary shaft for actuating the take-up and the needle threading devices, means for driving the secondary shaft from the sewing shaft, and driving and stopping mechanism for bringing the sewing shaft to rest with the needle disengaged from the work before the take-up reaches its stitch setting position, in combination with auxiliary mechanism set in operation by the driving and stopping mechanism while bringing the sewing shaft to rest for advancing the secondary shaft beyond the point to which it is driven by the sewing shaft to cause the take-up to set the final stitch in the seam.

122. A sewing machine having stitch forming devices including a hook needle, a needle looper, and a take-up, a main sewing shaft, driving and stopping mechanism for bringing the sewing shaft to rest with the needle disengaged from the work, and mechanism driven from the sewing shaft for actuating the stitch forming devices including a secondary shaft for driving the looper, in combination with means set into operation by the driving and stopping mechanism in bringing the main shaft to rest for driving the secondary shaft through a partial rotation to throw the looper out of sewing relationship with the needle.

123. A sewing machine having stitch forming devices including a hook needle, a needle looper, and a take-up, a main sewing shaft, driving and stopping mechanism for bringing the sewing

shaft to rest with the needle disengaged from the work, and mechanism driven from the sewing shaft for actuating the stitch forming devices including a secondary shaft for driving the looper, in combination with means set into operation by the driving and stopping mechanism in bringing the main shaft to rest for driving the secondary shaft through a partial rotation to throw the looper out of sewing relationship with the needle and set into operation by the driving and stopping mechanism in starting rotation of the main sewing shaft for rotating the secondary shaft relatively to the main shaft to restore the sewing relationship of the looper with the needle.

124. A sewing machine having stitch forming devices including a hook needle, a needle looper, and a take-up, a main sewing shaft, driving and stopping mechanism for bringing the sewing shaft to rest with the needle disengaged from the work, and mechanism driven from the sewing shaft for actuating the stitch forming devices including a horn transmission shaft mounted concentrically with the axis of horn rotation, a secondary looper driving shaft in the horn, and connections between the secondary shaft and the transmission shaft including a set of differential gears the members of which mesh with gears on the secondary and transmission shafts respectively, in combination with connections between the driving and stopping mechanism and the third member of the differential gear set for throwing the looper out of sewing relationship with the needle at the end of a seam.

125. A shoe sewing machine of the McKay type, having stitch forming devices including a straight hook needle operating from one side of the work, a rotatable work supporting horn at the other side of the work, a take-up and needle threading devices in the horn, a sewing shaft for actuating the stitch forming devices, and a secondary shaft in the horn driven by the sewing shaft to actuate the take-up and needle threading devices, in combination with driving and stopping mechanism for bringing the sewing shaft to rest and for causing the secondary shaft to be rotated relatively to the sewing shaft at the end of a seam.

126. A shoe sewing machine of the McKay type having stitch forming devices including a straight hook needle operating from one side of the work, a rotatable work supporting horn at the other side of the work, a take-up and needle threading devices in the horn, a sewing shaft for actuating the stitch forming devices, a secondary shaft in the horn driven by the sewing shaft to actuate the take-up and needle threading devices, and driving and stopping mechanism for bringing the sewing shaft to rest at the end of a seam in combination with auxiliary mechanism set in operation by the driving and stopping mechanism while bringing the sewing shaft to rest to rotate the secondary shaft relatively to the sewing shaft and while starting the sewing shaft at the beginning of a new seam, to return the secondary shaft and sewing shaft to their original positions relative to each other.

127. A shoe sewing machine of the McKay type having stitch forming devices including a straight hook needle operating from one side of the work, a rotatable work supporting horn at the other side of the work, a take-up and needle threading devices in the horn, a sewing shaft for actuating the stitch forming devices, a secondary shaft in the horn driven by the sewing shaft to actuate the take-up and needle

threading devices, and driving and stopping mechanism for bringing the sewing shaft to rest at the end of a seam, in combination with auxiliary mechanism for rotating the secondary shaft relatively to the sewing shaft including a two-position clutch set in operation by the driving and stopping mechanism while bringing the sewing shaft to rest to move into one position and set in operation a second time at the beginning of a new seam while starting the sewing shaft to move into a second position.

128. A shoe sewing machine having a vertically disposed straight hook needle, a rotatable work supporting horn mounted for rotation about a vertical axis, a needle threading looper at the tip of the horn, a main horizontal sewing shaft for actuating the needle, and a horn transmission shaft mounted concentrically with the axis of horn rotation for driving the looper, in combination with a single inclined shaft having bevelled driving and driven gears meshing with gears on the main shaft and the horn transmission shaft respectively.

129. A shoe sewing machine having a vertically disposed straight hook needle, a rotatable work supporting horn mounted for rotation about a vertical axis, a needle threading looper at the tip of the horn, a main horizontal sewing shaft for actuating the needle, and a hollow thread receiving horn transmission shaft mounted concentrically with the axis of horn rotation, in combination with a shaft inclined at an angle substantially less than ninety degrees to the transmission shaft for connecting the transmission shaft with the main shaft, a thread tension device beneath the lower end of the transmission shaft, and a cam on the connecting shaft for actuating the thread tension device during each sewing cycle.

130. A sewing machine having stitch forming devices including a needle and a take-up for setting each stitch in the work, a sewing shaft for actuating the stitch forming devices, driving and stopping mechanism for bringing the sewing shaft to rest with the needle disengaged from the work before the take-up reaches a stitch setting position, and a thread cutter, in combination with mechanism set in motion by the driving and stopping mechanism in bringing the sewing shaft to rest to cause the final stitch in a seam to be set and the thread cutter actuated after the sewing shaft has been brought to rest, a thread tension device, and means for relieving the tension on the thread after the thread cutter has been actuated.

131. A sewing machine having stitch forming devices including a straight hook needle, a rotatable work supporting horn, a sewing shaft for actuating the stitch forming devices, driving and stopping mechanism for bringing the sewing shaft to rest with the needle disengaged from the work, and a thread cutter arranged to be set in operation by the driving and stopping mechanism, in combination with means for preventing operation of the thread cutter while the horn is in a predetermined angular position.

132. A sewing machine having stitch forming devices including a straight hook needle, a rotatable work supporting horn, a sewing shaft for actuating the stitch forming devices, driving and stopping mechanism for bringing the sewing shaft to rest with the needle disengaged from the work, a thread cutter arranged to be set in operation by the driving and stopping mechanism, and

mechanism set in operation by the driving and stopping mechanism while bringing the sewing shaft to rest for actuating the thread cutter, in combination with connections between the horn and the thread cutter mechanism controlled by the angular position of the horn for preventing operation of the cutter with the horn in a predetermined angular position.

133. A sewing machine having stitch forming devices including a straight hook needle, a rotatable work supporting horn, a sewing shaft for actuating the stitch forming devices, driving and stopping mechanism for bringing the sewing shaft to rest with the needle disengaged from the work, a thread cutter arranged to be set in operation by the driving and stopping mechanism, an open cam, a spring actuated cam follower, and connections between the cam follower and thread cutter for actuating the cutter, in combination with a latch controlled by the position of the horn for holding the follower from movement while the horn is in a predetermined angular position.

134. A sewing machine having stitch forming devices including a straight hook needle, a sewing shaft for actuating the stitch forming devices, driving and stopping mechanism for the sewing shaft including a braking clutch, a lock bolt arranged to be actuated to throw the braking clutch into operation, a carrier on which the lock bolt is mounted for sliding movement toward and from operative position, a control member for moving the lock bolt in the carrier, a thread cutter, and mechanism including an auxiliary clutch for actuating the thread cutter, in combination with connections actuated by the control member for connecting the lock bolt carrier with the auxiliary clutch when the control member is moved to stop position to cause actuation of the thread cutter and for disconnecting the lock bolt carrier from the auxiliary clutch when the control member is moved to running position to cause the auxiliary clutch to be rendered active in performing other operations.

135. A sewing machine having stitch forming devices including a straight hook needle, a sewing shaft for actuating the stitch forming devices, driving and stopping mechanism for the sewing shaft including a braking clutch, a lock bolt arranged to be actuated to throw the braking clutch into operation, a carrier on which the lock bolt is mounted for sliding movement toward and from operative position, a control member for moving the lock bolt in the carrier, a thread cutter, and mechanism including an auxiliary clutch for actuating the thread cutter, in combination with shiftable abutments for throwing out the auxiliary clutch in either of two positions, connections actuated by the control member for connecting the lock bolt carrier with said abutments when the control member is moved to stop position to cause actuation of the thread cutter in stopping the machine and for disconnecting the lock bolt carrier from the said abutments when the control member is moved to running position to cause the auxiliary clutch to be rendered active in performing other operations.

136. A sewing machine having stitch forming devices including a straight hook needle, a work support and a presser foot, a sewing shaft for actuating the stitch forming devices, driving and stopping mechanism including a braking clutch, a lock bolt arranged to be actuated to throw the

75

braking clutch into operation, a carrier on which the lock bolt is mounted for sliding movement toward and from operative position, a lock bolt control member, a thread cutter, and mechanism including an auxiliary clutch for actuating the thread cutter and for disengaging the presser foot from the work, in combination with connections actuated by the control member for connecting the lock bolt carrier with the auxiliary clutch when the control member is moved to stop position to cause actuation of the thread cutter in stopping the machine and for disconnecting the lock bolt carrier from the auxiliary clutch when the control member is moved to running position to cause the presser foot to engage the work in starting the machine.

137. A sewing machine having stitch forming devices including a work support and a presser foot, a sewing shaft for actuating the stitch forming devices, driving and stopping mechanism, a foot treadle for controlling the driving and stopping mechanism, and mechanism for disengaging the presser foot from the work at the end of a seam, including an auxiliary clutch, in combination with abutments for throwing out the auxiliary clutch to bring the clutch to rest in either of two positions, a shaft rotated by the auxiliary clutch, a cam on the shaft, a cam follower for disengaging and engaging the presser

5
10
15

foot with the work, and connections between the foot treadle and the abutments for causing rotation of the auxiliary shaft to a position with the presser foot disengaged from the work when the foot treadle is moved to stop position and for throwing in the auxiliary clutch to bring the auxiliary shaft into a position with the presser foot engaging the work when the foot treadle is moved to running position.
